SWITCH AND SIGNAL CONTROL SYSTEM
FOR RAILROADS

Sedgwick N. Wight, Rochester, and Andrew Langdon, Brighton, N. Y., assignors to General Railway Signal Company, Rochester, N. Y.

Application December 13, 1938, Serial No. 245,384

14 Claims. (Cl. 246—134)

This invention relates to switch and signal control systems of the entrance-exit type for railways, and more particularly pertains to improvements in such systems as disclosed for example in the applications of A. Langdon, Ser. No. 119,641, filed January 8, 1937, and Ser. No. 176,466, filed November 26, 1937.

In an entrance-exit type system, the operator may control the power operation of track switches and the clearing of signals of a track layout, so as to provide any desired route for train movement over the track layout, by merely actuating freely movable control buttons or devices to designate the entrance and exit ends of such routes. These control buttons are preferably located on a miniature track diagram representing the actual track layout, at points on the diagram corresponding with the signal locations constituting entrance and exit ends of the routes over the track layout. Generally speaking, such an entrance-exit type of control system comprises suitable route selecting or establishing means and acts in response to the operation of control buttons to designate the entrance and exit ends of some particular desired route to control the appropriate switches to the positions required to establish that route, and also to effect the clearing of the signal at the entrance to that route when all of the track switches included in such route have properly responded to their control.

In a switch and signal control system, such as disclosed in the above mentioned prior applications and to which the present invention more particularly relates, the operation of the route establishing means involves a preliminary initiating or conditioning operation in response to the actuation of a control button to designate a signal location as an entrance point, and a completion operation in response to the actuation of a control button to designate the exit end of a particular route originating at the designated entrance point.

More specifically, the actuation of a control button to designate any given signal location as an entrance point energizes the initiating circuits and relays for preselecting the positions of certain switches of the track layout as may be required to conform with all of the various available routes originating at the designated entrance signal location, preparatory to the designation or identification of a particular one of such routes as the desired route to be established. The energization of appropriate initiating circuits acts to render effective for actuation or manipulation the control button for the exit

end of each of the routes originating at the designated entrance point only if that route is not in conflict with some other established route. There is no power operation of track switches during this preliminary initiating operation; but, when the operator actuates a control button to designate the exit end of a particular one of these available routes originating at the designated entrance signal location, a completion circuit means is rendered effective to cause operation of the track switches included in that route to positions required to establish that route by the energization of switch control relays in conformity with the pre-selecting operation performed by the initiating circuits, and at the time of the energization of these switch control relays the respective track switches are operated, if they are not already in proper positions. The energization of these switch control relays at the same time opens the initiating circuits relating to all other routes originating at the same entrance signal location.

A route establishing means operating in this manner to set up any desired route in response to the designation of the entrance and exit end of such route involves, among other things, a control of the continuity of the initiation circuits by contacts of the switch control relays of switches included in established routes in such a way that the initiating circuits relating to any given switch are not energized a portion of a route or a path for train movement from the designated entrance signal location to and over that switch in its pre-selected position is in conflict with any route then established, and also no operating potential is supplied to render the actuation of a control button effective to designate the exit end of a route unless there is some route to that exit end from the designated entrance signal location which is not in a conflict with any route that may then be established. In other words, the control of the continuity of the initiating circuits provides in effect an electric interlock between conflicting routes, and also serves to automatically select between alternative or optional routes dependent upon conflict of any established route with the respective alternative routes, in a manner shown and described more in detail in the above-mentioned prior application Ser. No. 176,466, filed November 26, 1937.

Another characteristic of the embodiment of the present invention is that the switch control relays, which govern the continuity of the initiating circuits and thus determine when a route

or portion thereof is in conflict with some route then established, are maintained energized by the presence of a train in the route, so that the interlock between conflicting routes and the automatic selection of optional routes is effective while a route is occupied by a train, as well as while a route is established by the route establishing means. In this connection, since the control buttons of the system are freely movable and might be manipulated to exercise a control to change the position of the switch in a route under or ahead of a train, the system includes route locking means of some suitable form to lock each switch in a route against power operation while a train is approaching or passing over that switch; and in the preferred embodiment of the invention illustrated, this same route locking means is employed to maintain the energization of the switch control relays, as by closing a stick circuit therefor, until the train entering a route has passed over the corresponding switch.

The system embodying the present invention also provides that the buttons operated to designate entrance signal locations, as well as the buttons for designating exit ends of routes, are of the self-restoring push button type and are automatically restored to a normal inactive condition after each manual actuation. The momentary actuation of an entrance push button is arranged to energize a stick relay, conveniently termed an entrance relay, which is maintained energized by its stick circuit until a train passes the corresponding signal location, whereupon the entrance relay is automatically deenergized with the same effect as when an entrance button of the stay-where-put type is manually restored upon passage of the train as disclosed in the above mentioned prior application Ser. No. 119,641. The stick circuit for the entrance relay is also arranged to be opened by manually operable contact means, preferably associated with the same button, so that the entrance relay may be manually restored to normal, whenever the operator so desires, as in the event a route is established prematurely or by mistake. In the specific arrangement illustrated, provision is made to open the stick circuit of an entrance relay only momentarily when a train passes the corresponding signal, so that the entrance relay can again be energized if desired by subsequent actuation of the button while a train is still present and thereby clear a signal for a following train to enter the occupied route, but this specific feature of control is optional and may be omitted where it is not desired to clear signals for train movement into occupied routes.

This invention also relates to what is termed through route control for a plurality of so-called interlocked groups. An interlocked group in this sense may be said to comprise a group of switches adapted to provide in their different positions certain routes between entrance and exit points, each of these routes conflicting with one or more others, and requiring some form of interlocking control to prevent conflicting routes being set up at the same time. An interlocked group may comprise, for example, two or more parallel tracks interconnected by one or more crossovers, with some or all of the parallel tracks also connected by one or more single switches to branch tracks or sidings.

When the track layout includes two or more such interlocked groups, there may be certain routes of these interlocked groups which may be set up at the same time in end-to-end relation,

so to speak, and provide a through route over two or more successive interlocked groups past one or more entrance signals for these routes which constitute in effect intermediate signals in the through route. Although these routes in end-to-end relation may be established for each interlocked group individually by entrance-exit control, it is desirable for various reasons to provide a through route control of the route establishing means of the respective interlocked groups in such a way that any through route may be established and the intermediate signals cleared merely by the actuation of buttons to designate the extreme entrance and exit ends of that through route, and without requiring manipulation of buttons for the intermediate signal locations.

A system involving a preselectiton and a completion operation in the manner above briefly explained and disclosed in the prior application Ser. No. 119,641, is well adapted for this desired through route control, particularly in connection with the automatic selection of only one of the different alternative through routes that the track layout may afford. Generally speaking, in order to provide the desired through route control, electrical connections for through route operation are provided for each signal, which may become an intermediate signal in some through route, for interconnecting the initiating circuits for adjoining interlocked groups with respect to these signals, so that the operation of a button to designate any entrance signal location is effective to energize the initiating circuits of all interlocked groups as may be required to conform with all of the through routes originating at that entrance signal location, as well as the routes over the interlocked group with which said entrance signal location is associated.

In other words, the initiating and preselecting effect is extended over successive interlocked groups preparatory to establishing routes in end-to-end relation over these interlocked group as may be required, and this preselecting action is dependent upon the availability of routes or portions thereof with respect to the interlocked groups as a whole in the same manner characteristic of a single interlocked group, so as to select automatically alternative through routes and render effective the operation of buttons to designate the exit ends of only those through routes available. After such preliminary initiating or preselecting operation, if the exit end of a through route is designated by the manual actuation of a button, the switches in the remote interlocked group are operated by the completion circuit means in accordance with the preselection to set up a route over that interlocked group connecting with a particular entrance signal thereof, and suitable relay means at that entrance signal is automatically energized by the completion circuit means to perform entrance and exit functions for that signal location so as to clear the corresponding signal and control the completion circuit means of the adjoining interlocked group in the same way as if buttons had been manipulated to designate that signal location as the entrance end of a route through the remote interlocked group and the exit end of a route connecting therewith through the adjoining interlocked group, the same operation being repeated for as many interlocked groups as may be involved.

In accordance with one feature of the im-

75
provement constituting this invention, when a portion of a through route is completed through an interlocked group, a through route relay for the corresponding intermediate signal location is energized by the completion circuits and acts to energize automatically the entrance relay for that signal and also exercise an exit control for the completion circuit means of the adjoining interlocked groups, this control exercised by said through route relay being effective only temporarily, so as not to interfere with the subsequent restoration of the entrance relay, or the proper operation of the route establishing means of the adjoining interlocked group by reason of any maintained exit control performed by the through route relay.

In connection with this through route control, there are various conditions under which the through route connections for the initiating circuits of the adjoining interlocked groups should be broken to prevent interference with the regular operation of setting up routes through different interlocked groups, and to avoid improper control of switches and signals by through route control under certain conditions. In the first place, the through route connections for each intermediate signal are opened when the corresponding signal is either the entrance or the exit end of an established route. In the arrangement of circuits illustrated, the through route connection for each intermediate signal includes back contacts of the corresponding entrance relay and exit relay.

Another feature is that the through route connections for each intermediate signal are broken by suitable track circuit controlled means whenever a route terminating at that signal is occupied by a train irrespective of the direction of movement of the train when entering said route. In the specific embodiment of the invention illustrated, this desired control of the through route connections is accomplished by including in said connections associated with an intermediate signal the front contact of the track relay or relays for the track section or sections in any possible route extending to that signal, these track relay contacts serving to interrupt the through route connections when a train is present regardless of the direction in which the train entered the corresponding track section.

Considering a further feature of the control of the through route circuit connections, when a train traverses a through route, the intermediate signals are automatically caused to assume the stop condition as the train passes each signal by the automatic deenergization of the corresponding entrance relay; and in connection with this automatic restoration, provision is made in accordance with this invention so that the through route connections for an intermediate signal are not closed when a train passes that signal until the route establishing means for the route originating at that signal is effectively deenergized. This route establishing means includes among other things an exit stick relay or equivalent; and if the through route connections were not thus kept open, this relay might be maintained energized improperly, if the train should happen to pass the intermediate signal and deenergize its entrance relay at the time the initiating circuits for the adjoining interlocked group had been energized by the operation of some entrance button. In the specific embodiment of the invention illustrated, each of the through route connections are controlled by the

front contact of a relay M which is closed only when the corresponding signal has assumed its stop condition; and when an entrance relay is deenergized by a passing train, this relay acts to keep open the through route connections temporarily until the signal has assumed its stop condition, and long enough for the exit stick relay to be effectively deenergized and cause the completion circuit means to assume its normal condition. 5

Another feature of the through route control characterizing this invention is that through routes may not be established to allow a train to move from the track layout under the operator's control into a stretch of track in a direction opposite to the direction of traffic for which this stretch of track is normally used. It is contemplated that the through route control will be ordinarily used by the operator for through train movement as distinctive from switching or shunting train movements; and it is considered desirable that such through route control should not be used by the operator carelessly or accidentally to direct a train into a stretch of track against the normal direction of traffic. The operator may establish a route through an interlocked group into an adjoining stretch of track against the normal direction of traffic by manipulation of the entrance and exit control buttons for that particular interlocked group, when a shunting train movement or other condition may require, but cannot do so by through route control. Generally speaking, in accordance with this invention, an extra selector relay is employed, which is responsive to the energization of initiating circuits by the through route connections, but not by the operation of the corresponding entrance button, to interrupt the appropriate initiating circuits and render ineffective the manual actuation of a button to designate the exit end of a through route which would direct a train into a stretch of track against the normal direction of traffic. 35

45
50
55
60
65
70
75

Another feature of the present invention relates to the automatic selection of optional or alternative routes that may be afforded by the track layout. In the type of system disclosed in the prior application Ser. No. 176,466 above mentioned, optional routes are automatically selected by preselecting the position of each trailed crossover switch, or crossover required to be in different positions for the optional routes for operation by the completion circuit means to the normal position in preference to the reverse position, with the result that the preferred optional route is that one over the remote crossover or crossovers in the normal position and the crossover nearest the entrance signal in the reverse position. 45
50
55
60
65
70
75

Under certain special conditions, however, it may be desirable to have the preferred optional route, which is established unless some conflict exists, include the remote crossover in the reverse position instead of the normal position. For example, the remote crossover may be more suitable for train movement at high speed than the near crossover, or perhaps it may be expedient to use the remote crossover in its reverse position for the preferred optional route so that trains may be brought to a certain platform or other track location. In view of these contingencies, the improved system of this invention provides means by which the preferred or superior optional route ordinarily obtained is over the remote crossover in the reverse position, rather 75

than the normal position. In one arrangement, the preselecting or route selector relay for this remote crossover is arranged to be energized by initiating circuits corresponding to the reverse 5 position of this crossover, and to act when energized to cause this crossover to be operated to the reverse position by the completion circuit means. According to another arrangement, the initiating circuit for preselecting the normal position of the remote crossover is normally kept 10 open by a special selector relay, and is not closed unless one end of this crossover in the normal position is included in some established route, so that this crossover cannot be used in the reverse 15 position for the superior optional route.

A still further feature of this invention relates to the provision of an electric interlock between the exit relays of adjoining interlocked groups, so that two routes over these interlocked groups 20 cannot be set up contemporaneously toward the same signal location constituting the common exit end of these routes. This serves as a check upon the manipulation of the buttons by the operator, so that he will not carelessly or accidentally 25 establish routes at the same time to bring opposing trains up to the same signal location. Also, the entrance relays for the same signal location and adjoining interlocked groups are provided with electric interlocking circuits as 30 a further check upon the operator's manipulation of the control buttons.

Other objects, purposes and characteristic features of the present invention will be in part obvious from the accompanying drawings, and in 35 part pointed out as the description of the invention progresses.

In describing the invention in detail, reference will be made to the accompanying drawings, in which like reference characters designate corresponding parts throughout the several illustrations, similar letter reference characters being used to designate parts of a similar nature which are generally made distinctive by preceding numerals, and in which:

40 Figs. 1A, 1B and 1C, when placed end-to-end above Figs. 1D, 1E and 1F respectively, illustrate the self-selecting network provided for this particular embodiment of the present invention;

45 Fig. 2 illustrates certain typical circuits relative to the track switch and signal controls; and

50 Figs. 3A and 3B, when placed end-to-end, illustrate the track layout and signal controls for this embodiment of the present invention.

In considering various parts of a similar nature 55 from time to time during the disclosure, reference is made in a general manner to those parts by letter reference characters without their preceding numerals. It is to be understood that such a reference applies to any parts designated 60 in the drawings by reference characters that are similar except for numerals associated therewith.

The various parts and circuits constituting the embodiment of the present invention have been 65 shown diagrammatically and certain conventional illustrations have been employed for the purpose of simplifying the illustration and facilitating in the explanation of the invention. The drawings are made more for the purpose of facilitating 70 the disclosure of the invention as to the principles involved and the mode of operation, than for the purpose of illustrating the specific construction and arrangement of parts that would be employed in practice. Thus, the various 75

control buttons and other apparatus are illustrated in a conventional manner, and symbols are used to indicate connections to the terminals of batteries or other sources of electric current instead of showing all of the wiring connections to those terminals.

The symbols (+) and (-) are employed to indicate the positive and negative terminals respectively of suitable batteries, or other sources of direct current; and the circuits with which those symbols are used always have current flowing in the same direction. If alternating current is used instead of direct current, the symbols should be considered to represent the instantaneous relative polarities applied to the circuits. It is to be understood that certain of the various circuits can be energized from a common battery and that several batteries can be provided where required in practice.

To facilitate in the disclosure of the present 20 invention, various relays and circuits are shown in duplicate on various pages of the drawings, and those relays and circuits shown having corresponding reference characters are to be considered identical.

Apparatus

Track layout.—With reference to Figs. 3A and 3B, two parallel tracks have been illustrated as connected together at various points by crossovers having track switches 2TSA, 2TSB, 3TSA, 3TSB, 4TSA and 4TSB.

These parallel tracks with connecting crossovers and associated signals constitute two interlocked groups. One of these interlocked groups 35 includes the crossovers 2 and 3 for providing routes between the signals 10 and 11 at one end of the interlocked group and the signals 12 and 13 at the other end of the interlocked group; and the interlocked group comprises the crossover 4 to provide routes between signals 14, 15, 16 and 17. It will be noted that the crossovers 3 and 4 are so disposed as to provide alternative or optional through routes between the signals 10 and 17, this arrangement being shown to illustrate 40 how the principles of this invention may be employed to select a superior or preferred optional through route. It should be understood that this invention is applicable to various arrangements of single tracks, switches, crossovers, 45 and the like, of any conventional track layout; and the track layout shown represents merely one simple arrangement to illustrate the nature of the invention.

The track switches are positioned by power operated switch machines which can be of any suitable type such, for example, as the switch machine shown in the patent to W. K. Howe, Patent No. 1,466,903, dated September 4, 1923. The motors of the switch machines can be controlled 60 in any suitable manner, such, for example, as in the patent to W. H. Hoppe, et al., Patent No. 1,877,876, dated September 20, 1932. If the switch machine motors are controlled in accordance with that Hoppe et al. patent, the relay CR of that 65 patent is controlled by the relay WZ illustrated in Fig. 2 of the present disclosure.

In order to simplify the present disclosure only one switch machine SM has been shown for each crossover, because the track switches for both 70 ends of the crossovers should usually assume corresponding positions. Thus, switch machine 2SM has been provided for positioning track switches 2TSA and 2TSB, switch machine 3SM has been provided for positioning track switches 75

3TSA and 3TSB and switch machine 4SM has been provided for positioning track switches 4TSA and 4TSB. It is to be understood that a separate switch machine SM can be provided for governing each track switch in accordance with the requirements of practice.

A polar neutral relay WP is provided for each crossover for repeating the locked position of the track switches in correspondence with the locked position of the switch machine. That is, relay 2WP, for example, is energized with one polarity when the switch machine 2SM is in a normal locked position and the track switches 2TSA and 2TSB are locked normal, and that relay is energized with the opposite polarity when switch machine 2SM is in a reverse locked position and track switches 2TSA and 2TSB are locked reverse. Relay 2WP is dropped away whenever either of the two above conditions are not completely satisfied. The control circuits for the relays WP are selected to provide such a mode of operation by point detector contact mechanisms such as the type shown, for example, in the patent to C. S. Bushnell, Patent No. 1,517,236, dated November 25, 1924.

Signals 10, 11, 14 and 15 have been provided for governing east bound traffic, to the right, and signals 12, 13, 16 and 17 have been provided for governing west bound traffic, to the left.

The signals have been illustrated as being of the search light type. The search light type signals can be of a type such as is shown, for example, in the patent to O. S. Field, Patent No. 1,835,150, dated December 12, 1931. Each of the signals illustrated in this disclosure is provided with contacts closed only when the signal is at stop, as shown in that Field patent, for energizing a signal at stop repeater relay M associated with that signal. The signals are considered to provide a normal-at-stop red indication and a clear green indication. It is also to be understood that a yellow indication for caution can be provided if such indication is required in practice, and that other types of signals could as well be employed in accordance with the present invention, such, for example, as signals having individual color lamp units or signals of the semaphore type.

The track layout has been divided into track sections by the usual insulated joints to provide the usual track circuits for the track relays. Track sections 6, 7, 8 and 9 have been shown as having associated therewith track relays 6T, 7T, 8T and 9T respectively. Slow acting track repeater relays 6TP, 7TP, 8TP and 9TP are provided for track relays 6T, 7T, 8T and 9T respectively. It is of course to be understood that the number of track circuits can be varied in accordance with the requirements in practice from the particular track circuit arrangement illustrated in the present disclosure. The track circuits are assumed to be of the usual normally energized type, and the track switches are assumed to be properly bonded to provide fouling protection, all of which details have not been shown in order to simplify the present disclosure, because those details are well known to those familiar with the art.

Control machine.—The control machine provided for governing traffic through the track layout heretofore described, has a control panel upon which is constructed a miniature track diagram (see Figs. 1A, 1B and 1C) corresponding to that track layout. The miniature track diagram is provided with suitable indication means along

the diagram sections representative of the track sections and track switches to provide necessary indications with respect to routes that have been established, the presence of trains on the sections, and the indication of the signals at the various points in the track layout. Inasmuch as this invention relates more particularly to the use of a self-selecting network in setting up the various routes, those indications have not been shown. Such indications can be provided as shown and described in the prior Hitchcock application, Ser. No. 74,709, filed April 16, 1936, and in the prior Langdon application, Ser. No. 176,466, filed November 26, 1937.

An entrance button NB is provided on the 15 miniature track diagram for the entrance point to each route as defined at the track layout by the location of the signals. Thus, buttons 10NB, 11NB, 12NB, 13NB, 14NB, 15NB, 16NB and 17NB have been provided on the control panel as representative of entrance points at signals 10, 11, 12, 13, 14, 15, 16 and 17 respectively. The buttons are located on the miniature track diagram at positions corresponding to the positions of the signals at the track layout for governing entrance at those entrance points. Each entrance button NB is of the push-pull button type. That is, the button is biased to a normal position from which it can either be depressed or pulled out. There is an operating contact on the button which is closed when the button is depressed, and there is a normally closed contact on the button which is closed when the button is in its normal position as well as when it is depressed. When the button is pulled out, the normally closed contact is opened. The construction and contact arrangement for such a push button can be provided, for example, as shown in the application of J. F. Merkel, Ser. No. 158,720, filed August 12, 1937.

An exit button XB is provided for the exit end of each possible route in the track layout, and the exit buttons are located on the track diagram at positions corresponding to the actual exit points in the track layout. Exit buttons 10XB, 11XB, 12XB, 13XB, 14XB, 15XB, 16XB and 17XB are provided for exit points at signals 10, 11, 12, 13, 14, 15, 16 and 17 respectively. The exit buttons XB are of the self-restoring push button type, each having a contact closed only when that button is depressed.

Although separate push buttons have been illustrated for each entrance and exit point associated with each signal, it is to be understood that other forms of control switches could as well be used for those points, and that the entrance and exit buttons for each signal location could as well be combined into a single control switch having distinctive positions to provide the selection of the circuits necessary in accordance with the present invention. It is also to be understood that the distinctive entrance and exit control contacts can be included on one push button with circuit means provided for distinction such as is shown, for example, in the Preston application Ser. No. 183,499, filed January 5, 1938.

A switch control lever SML is provided on the control panel for each crossover, as is typically shown in Fig. 2 for governing track switches 4TSA and 4TSB, the lever 4SML having a normal center position, a left hand position for operating the associated track switches to a normal position, and a right hand position for operating the associated track switches to a re-

verse position. Contacts are provided on the lever for each of those positions.

System devices.—With reference to Figs. 1A, 1B, 1C, 1D, 1E and 1F, each of the entrance buttons NB has associated therewith an entrance or repeater relay NR which is picked up in response to the depression of that entrance button, and maintained energized dependent upon the passage of a train, or the actuation of a button for manual restoration to normal.

An exit relay XR is provided for each exit point in the track layout, and that exit relay is picked up when a route is set up having an exit point with which that relay is associated. Each relay XR is maintained picked up dependent upon the entrance relay NR for the route with which that exit point is associated.

A relay AY or BY is provided for each of the track switches for initially selecting the position of that track switch in accordance with the defining of each entrance point by the depression of an entrance button. Relays 2AY, 3AY and 4AY have been illustrated as being associated with track switches 2TSA, 3TSA and 4TSA respectively, and relays 2BY, 3BY and 4BY have been illustrated as having been associated with track switches 2TSB, 3TSB and 4TSB respectively. Special route selector relays 3YY and 4YY have been provided for governing the control circuits of certain of the Y relays.

The relays AN, BN and R are provided for causing the operation of the track switches in accordance with routes defined by an operator by the operation of buttons for entrance and exit points. Relays 2AN, 3AN and 4AN are provided for causing the operation of the track switches of crossovers 2ts, 3ts and 4ts to a normal position in accordance with the setting up of routes including that position for the track switches 2TSA, 3TSA and 4TSA respectively. Relays 2BN, 3BN and 4BN are provided for causing the operation of the track switches for the crossovers 2ts, 3ts and 4ts respectively, to a normal position in accordance with the setting up of routes including that position for track switches 2TSB, 3TSB and 4TSB respectively. Relays 2R, 3R and 4R are provided for causing the operation of the track switches for crossovers 2ts, 3ts and 4ts respectively to reverse positions. The relays AN, BN and R are picked up, in accordance with pick up circuits selected by the Y relays, upon the designation of an exit point during the setting up of a route.

A slow release relay XP is associated with the entrance and exit relays through route control provided for each intermediate signal for the purpose of setting up routes initiated by end-to-end control.

Each of the detector track sections is provided with a normally energized lock relay L as is typically shown in Fig. 2 of the accompanying drawings, relays 8L and 9L having been provided for the detector track sections associated with track switches 4TSA and 4TSB. The control circuits for the relays L have been shown as including contacts of route locking relays ES and WS which are provided for the various track sections in accordance with the requirements of practice. Inasmuch as it is contemplated that such route locking relays ES and WS be controlled as shown in prior applications, the circuits for those relays have not been shown as reference can be made to other applications for the manner in which they are controlled, such as the prior application of A. Langdon, Ser. No. 176,466, filed

November 26, 1937. If approach locking is to be used as well as route locking the relays ES and WS can be controlled in a manner similar to that shown for relays bearing similar letter reference characters in the patent to C. F. Stoltz, Patent No. 2,115,511, dated April 26, 1938. It is to be understood that other forms of route and approach locking can as well be used with the entrance-exit system provided by the present invention.

A normally energized lock repeater relay LS is provided for each crossover as is typically shown in Fig. 2 of the accompanying drawings, in which relay 4LS is shown as a repeater of the relays L provided for that crossover.

A polar neutral switch control relay WZ is provided for controlling the switch machines for each crossover in accordance with the position of the switch control relays AN, BN and R for that particular crossover. Inasmuch as each relay WZ has a similar mode of operation, only the detail circuits for relay 4WZ has been shown, those circuits being typical of the circuits provided for the relays WZ associated with the other crossovers included in the track layout.

Correspondence relays NCR and RCR are provided for each crossover for repeating the position of the track switches in correspondence with the position of the relays AN, BN and R for those track switches. Relays 4NCR and 4RCR have been shown as typical of the correspondence relays provided for each of the crossovers.

A signal control relay G (see Figs. 3A and 3B) is provided for governing each signal, each relay G being energized only when a route has been completely established having that signal as an entrance point.

Having thus considered the apparatus provided in accordance with the present invention, the mode of operation of the system is herein-
after disclosed more in detail in considering various typical operations of the system.

Operation

Normal conditions.—The normal conditions of the system are considered as those conditions which exist when the track sections illustrated are unoccupied, the signals are all at stop, and when there are no entrance or exit points defined by the operation of buttons for those points. An operator is informed of such normal conditions by the various indicator lamps (not shown) which are extinguished under such conditions to provide a "normally dark board" with respect to the illumination of the indicator lamps.

Under normal conditions the track switches are in their last operated positions, which, for illustration of the present disclosure, has been assumed to be the positions providing through routes on each of the parallel tracks.

Of the relays associated with the self-selecting network, only the special route selector relay 3YY is normally energized. The circuit by which relay 3YY (see Fig. 1B) is energized is closed from (+), through a circuit including back contact 20 of relay 4AN (see Fig. 1C), wire 82, contact 21 of button 13XB closed in a normal position, back contact 22 of relay 13XR, back contact 23 of relay 3R, and winding of relay 3XY, to (-).

The lock relays L are normally energized as is typically shown for relays 8L and 9L (see Fig. 2). A circuit is closed for the energization of relay 8L from (+), through a circuit including front contact 24 of relay 8T, front contact 221 of relay 8ES, front contact 222 of relay 8WS,

winding of relay 8L, and front contact 25 of relay 8L, to (-). A circuit for maintaining relay 9L picked up under normal conditions is closed from (+), through a circuit including front contact 26 of relay 9T, front contact 223 of relay 9ES, front contact 224 of relay 9WS, winding of relay 9L, and front contact 27 of relay 9L, to (-).

With the lock relays L in a picked up position, a circuit is closed, under normal conditions, for each of the lock repeater relays LS, as is typically shown by the circuit for relay 4LS closed from (+), through a circuit including front contact 28 of relay 8L, front contact 29 of relay 9L, back contact 30 of relay 4WZ, and winding of relay 4LS, to (-).

In accordance with the last operated positions of the track switches, as illustrated in Figs. 3A and 3B, the correspondence relay NCR for each of the crossovers is normally energized as is typically shown for relay 4NCR (see Fig. 2). Relay 4NCR is energized under such conditions by a circuit closed from (+), through a circuit including back contact 31 of relay 4R, winding of relay 4NCR, polar contact 32 of relay 4WP in a right hand position, and front contact 33 of relay 4WP, to (-).

The signal repeater relay M provided for each signal is normally energized by a circuit similar to the circuit typically shown for relay 15M. Relay 15M is normally energized by a circuit closed from (+), through a circuit including contact 34 of signal 15 at stop and winding of relay 15M, to (-).

Initiating and completion circuits.—As already generally outlined and explained more in detail in the prior application Ser. No. 119,641, the operation of establishing a route in accordance with the mode of operation characterizing this invention involves the energization of initiating circuits in response to the actuation of any given entrance button to preselect the position of trailel switches included in all of the various routes originating at the corresponding entrance signal location, and also to supply an operating potential to the exit relays for the exit ends of all of these routes then available. In the specific arrangement illustrated, these initiating circuits are arranged in the form of a network, one for each direction of train movement; and the circuit branches of the network are arranged to control the energization of preselecting or route selector relays AY and BY associated with the switches at the ends of the crossovers. The energized or deenergized condition of these route selector relays determines the position to which the corresponding switch is operated by the completion circuit means. With the exception of certain route selector relays specially controlled for optional route selection in a manner later explained, each route selector relay is energized when the corresponding switch is trailel in a normal position in some route originating at the entrance signal location designated by the manual actuation of an entrance button, the route selector relay for a switch trailel in the reverse position being left deenergized, and the route selector relay for a facing point switch being unaffected.

After such an initiating or conditioning operation as a result of the energization of the appropriate route selector relays, the manual actuation of an exit button for a particular one of the available routes originating at the designated entrance signal location acts to energize an exit relay, which supplies current to completion cir-

cuits to cause energization of the appropriate switch control relays of the switches involved in this particular route, this energization of the switch control relays acting to open the initiating circuits relating to all other routes originating at the same entrance signal location.

To consider an example of how a route is set up within an interlocked group, assume an operator, after checking his indicator lamps to find that the proposed route is available, depresses entrance button 14NB. The depression of button 14NB causes the picking up of relay 14NR by closing a circuit from (+), through a circuit including contact 35 of button 14NB closed in a depressed position, wire 83, back contact 36 of relay 12NR, wire 84, front contact 37 of relay 8T, and winding of relay 14NR, to (-). The picking up of relay 14NR closes a stick circuit for maintaining that relay picked up from (+), through a circuit including contact 35 of button 14NB closed in both a depressed and a normal position, front contact 38 of relay 14NR, wire 83, back contact 36 of relay 12NR, wire 84, front contact 37 of relay 8T, and winding of relay 14NR, to (-). In each of the above described circuits, back contact 214 of relay 8TP is connected in the circuit in multiple with front contact 37 of relay 8T to provide that the circuits can be closed again immediately upon entrance of a train into track section 8 if it is desired to set up a route at that time for a following train.

It is to be understood that the back contacts of the track repeater relays TP, connected in multiple with the front contacts of the track relays T in the stick circuits for the entrance relays NR, can be eliminated in conditions encountered in practice where it is not required that an operator be permitted to set up a route for a following train when the preceding train is occupying the track section immediately beyond the entering signal to that route.

The energization of the entrance relay 14NR and the closing of its contact 39 supplies current to the appropriate initiating circuits which function is to preselect the position of the trailel switches included in the various routes originating at this entrance signal location. In the example under consideration, where the entrance relay 14NR is energized, the only switch in a trailing relation to the corresponding entrance signal 14 is the lower end of the crossover 4, and since this switch is trailel in the reverse position, no route selector relay is energized.

The initiating circuits also supply an operating potential to the exit relays of the various available routes originating at a designated entrance point. In the case under consideration, operating potential is supplied to the exit relay 17XR over an initiating circuit from (+), front contact 39 of entrance relay 14NR, back contact 40 of relay 14XR, back contact 41 of switch control relay 14AN, back contact 42 of switch control relay 14BN, contact 43 of route selector 4BY, to one terminal of the winding of the relay 17XR. This initiating circuit includes back contacts 41 and 42 of the switch control relays 14AN and 14BN, so that if a route over either end of the crossover 4 in the normal position is established, such routes being necessarily in conflict with any route between the signals 14 and 17, the initiating circuit just traced is open, and any operation of the exit button 17XB is not effective to energize the exit relay 17XR. There is a similar initiating circuit for supplying an operating

potential to the exit relay 16XR through the back contact 212 of the special selector relay 4YY, for reasons later explained, back contact 213 of switch control relay 4RR to one terminal 5 of the exit relay 16XR. This initiating circuit for a route from signal 14 to signal 16 over the upper end of the crossover 4 in the normal position is broken by the contact 213 if the switch control relay 4R is energized for any conflicting route over the crossover 4 in the reversed position.

Assuming that the operator selects the signal 17 as the exit end of the desired route and operates the exit button 17XB, the exit relay is energized by the flow of current over the initiating circuit above traced through the back contact 44 of the entrance relay 17NR, contact 45 of exit button 17XB, to (—). This energization of the exit relay 17XR closes its contact 46 to provide a shunt for the contact of the exit button, so 15 that the exit relay is maintained energized after the exit button is released and restored to its normal position.

This energization of an exit relay supplies energy to a completion circuit network to energize 25 the appropriate switch control relays to establish the desired route. In the example under consideration, upon energization of the exit relay 17XR, the reverse switch control relay 4R (see Fig. 1F) is picked up when its circuit is closed from (+), 30 through a circuit including front contact 47 of relay 17XR, back contact 48 of relay 4BY, upper winding of relay 4R, back contact 49 of relay 4BN, and back contact 50 of relay 4AN, to (—). The picking up of relay 4R causes the operation 35 of the track switches 4TSA and 4TSB to a reverse position in a manner hereinafter described when considering further details of the control for the track switches.

To consider another example of how the setting up of routes is accomplished within an interlocked group, assume an operator performs manipulations to set up a route from signal 15 to signal 17 when that route is available, and the system is initially under the normal conditions 40 shown and described.

In response to the depression of button 15NB (see Fig. 1C), relay 15NR is picked up when a circuit is closed of a similar character to that circuit described for the picking up of relay 50 14NR. Relay 15NR, when picked up, is maintained picked up by a circuit similar to the stick circuit described in detail for relay 14NR.

The picking up of relay 15NR, under such conditions, causes the picking up of relay 4BY when 55 a circuit for that relay is closed from (+), through a circuit including front contact 51 of relay 15NR, back contact 52 of relay 15XR, back contact 53 of relay 4R, and winding of relay 4BY, to (—).

The picking up of relay 4BY allows the picking up of relay 17XR when its circuit is closed upon the depression of the exit button 17XB by an operator, from (+), through a circuit including front contact 51 of relay 15NR, back contact 52 60 of relay 15XR, back contact 53 of relay 4R, front contact 43 of relay 4BY, winding of relay 17XR, back contact 44 of relay 17NR, and contact 45 of button 17XB closed in a depressed position, to (—). The closing of front contact 46 of relay 70 17XR provides stick energy for the circuit just described to maintain relay 17XR picked up after button 17XB is restored to normal.

When relay 17XR is picked up, after entrance and exit points have been defined by the operator as being at signals 15 and 17 respectively,

a pick up circuit is closed for relay 4BN (see Fig. 1F) from (+), through a circuit including front contact 47 of relay 17XR, front contact 48 of relay 4BY, upper winding of relay 4BN, and back contact 54 of relay 4R, to (—).

By describing the mode of operation of the self-selecting network for setting up a route over crossover 4ts requiring its track switches in a reverse position, and by describing the mode of operation in setting up a route requiring track 10 switch 4TSB to be normal, the use of the route selector relay 4BY to select between relays 4R and 4BN has been illustrated; that is, relay 4R is energized when relay 17XR is picked up if relay 4BY is in a dropped away position, and relay 15 4BN is energized when relay 17XR is picked up if relay 4BY is in a picked up position. Such mode of operation is characteristic of this entrance-exit system, irrespective of the number of track switches included in each route to be 20 set up.

Switch controls.—After considering the mode of operation of the system for setting up routes within an interlocked group, consideration is now given to the means provided for controlling the 25 track switches in accordance with the picking up of the switch control network relays AN, BN and R, and in accordance with the operation of an auxiliary switch control lever SML provided for each crossover. Inasmuch as the track 30 switches for each crossover are controlled in a similar manner, many of the details for the switch control have been shown only for crossover 4ts. It is to be understood that the circuits shown for crossover 4ts are typical of the 35 circuits provided for governing the track switches for each of the other crossovers included in the track layout, and it is also to be understood that similar circuits are provided in practice, as required, for governing single track switches.

With reference to Fig. 2, assume relay 4R to be picked up in setting up a route as heretofore described, for example, from signal 14 to signal 17. The picking up of relay 4R, with relay 8L, 45 9L and 4LS picked up as described when considering the assumed normal conditions, closes a circuit for the energization of the lower winding of relay 4WZ from (+), through a circuit including front contact 28 of relay 8L, front contact 29 of relay 9L, front contact 55 of relay 5R, and lower winding of relay 4WZ, to (—). The picking up of relay 4WZ, due to such energization, causes the operation of the polar contacts for that relay to a left hand position, and the energization of the switch machine 4SM to operate 50 55 the associated track switches to a reverse position. Such energization is effected upon the closing of an obvious circuit including front contacts 56 and 57 of relay 4WZ.

The picking up of relay 4R, in getting up the 60 assumed route, causes the dropping away of relay 4NCR by opening its circuit at back contact 31, thus relay 4LS is maintained picked up after relay 4WZ is picked up to open its pick up circuit at back contact 30, by a circuit closed from (+), through a circuit including front contact 28 of relay 8L, front contact 29 of relay 9L, back contact 58 of relay 4RCR, back contact 59 of relay 4NCR, front contact 60 of relay 4LS, and winding of relay 4LS, to (—).

As soon as the track switches 4TSA and 4TSB have been locked in their reverse positions in setting up a route from signal 14 to signal 17, the relay 4WP is picked up when energized with a polarity to operate its polar contacts to a left 75

hand position, and the picking up of that relay closes a circuit for relay 4RCR, from (+), through a circuit including back contact 61 of relay 4AN, back contact 62 of relay 4BN, winding of relay 4RCR, polar contact 32 of relay 4WP in a left hand position, and front contact 33 of relay 4WP, to (-). The picking up of relay 4RCR, due to such energization, causes the dropping away of relay 4LS by opening its stick circuit at back contact 58. The dropping away of relay 4LS closes the signal control circuit for signal 14 as is hereinafter described in considering the detail of the signal control circuits.

When relay 4WP is dropped away as soon as either of the track switches 4TSA and 4TSB have been unlocked from their normal position, a stick circuit is closed for relay 4WZ from (+), through a circuit including back contact 63 of relay 4WP, front contact 64 of relay 4WZ, polar contact 65 of relay 4WZ, in a left hand position, and lower winding of relay 4WZ, to (-). Such stick circuit provides that relay 4WZ is maintained picked up to complete the operation of the switch machine, irrespective of the dropping away of relay 4R, in case an operator cancels the proposed route before the switch machine 4SM has completed its operation.

A similar mode of operation is effected when the track switches are operated from a reverse to a normal position. For example, assume a route to be initiated from signal 15 to signal 17 when the normal conditions of the system exist as described. The picking up of relay 4BN in setting up such a route in a manner heretofore described, causes the picking up of relay 4WZ when a circuit is closed for the upper winding of that relay from (+), through a circuit including front contact 28 of relay 8L, front contact 29 of relay 9L, front contact 67 of relay 4BN, and upper winding of relay 4WZ, to (-). The picking up of relay 4WZ with its polar contacts operated to a right hand position closes an obvious circuit at front contacts 56 and 57 for causing the operation of the switch machine 4SM to a normal position. If the switch machine 4SM is already in a normal position at the time relay 4WZ is picked up, the picking up of relay 4WZ causes the dropping away of relay 4LS to close the signal control circuit by opening its circuit at back contact 30, because the correspondence relay 4NCR remains picked up to hold open the stick circuit for relay 4LS at back contact 59.

If, however, switch machine 4SM is in a reverse position prior to its energization for operation to a normal position, the picking up of relay 4BN opens the above described energized circuit for relay 4RCR to cause that relay to drop away and close back contact 58 in the stick circuit for relay 4LS to cause relay 4LS to be maintained picked up by the stick circuit heretofore described until the track switches 4TSA and 4TSB have been operated to a normal and locked position. The locking of the track switches 4TSA and 4TSB together with the switch machine 4SM in a normal position causes the energization of relay 4WP with its polar contacts operated to a right hand position to cause the picking up of relay 4NCR when its circuit heretofore described is closed. When relay 4NCR is picked up, the stick circuit for relay 4LS is opened at back contact 59 to cause that relay to drop away and close the signal control circuit.

When relay 4WZ is picked up for operating the switch machine 4SM to a normal position,

a stick circuit is closed during the operation of the switch machine to provide that the switch machine will complete its operation, from (+), through a circuit including back contact 63 of relay 4WP, front contact 64 of relay 4WZ, polar contact 65 of relay 4WZ in a right hand position, and upper winding of relay 4WZ, to (-).

Each of the track switches has an auxiliary control means provided by a switch control lever SML which has a normal center position, a normal operating position shown to the right (see Fig. 2) and a reverse operating position shown to the left.

It is provided that the lock relays L can be picked up only when the auxiliary switch control lever SML for that track switch is in a normal position. Such a mode of operation provides that the track switches can be operated only when the lock relays have had an opportunity to pick up prior to the operation of the switch control lever SML from its normal center position. Thus it is provided that the operation of the lever SML to an operating position causes the operation of the track switches only if those track switches can be positioned at the time the lever is operated. Such a means for preventing the preconditioning of track switches is conveniently called by those familiar with the art "lever lock equivalent".

An example of the pick-up circuits provided for the lock relays for each of the track switches is shown in Fig. 2 in which relay 8L, for example, is picked up only when the detector track section 8 is unoccupied by a train and lever 4SML is in its normal center position. The pick-up circuit is closed under such conditions from (+), through a circuit including front contact 24 of relay 8T, front contact 221 of relay 8ES, front contact 222 of relay 8WS, winding of relay 8L, and contact 68 of lever 4SML in a normal center position, to (-).

When lever 4SML is operated to a right hand normal operating position, at a time when the above described normal conditions of the system exist, relays 4AN and 4BN are picked up when their center windings are energized. The operation of lever 4SML to a normal operating right hand position closes a circuit for relay 4AN from (+), through a circuit including contact 69 of lever 4SML in a right hand position, center winding of relay 4AN, and back contact 70 of relay 4R, to (-). In a similar manner the closing of contact 71 in a right hand position effects the energization of an obvious circuit for relay 4BN. The picking up of relays 4AN and 4BN cause the energization of relay 4WZ and the operation of the switch machine to a normal locked position in the same manner as heretofore described when relay 4BN was assumed to be picked up in setting up a route by operation of the control buttons for the entrance and exit points.

If lever 4SML is operated to a reverse operating left hand position, when the above described normal conditions of the system exist, relay 4R is picked up when its obvious circuit is energized for its center winding upon the closing of contact 69 of lever 4SML in a left hand reverse operating position. The picking up of relay 4R under such conditions of course causes the operation of the switch machine 4SM to a reverse position the same as described when that relay was assumed to be picked up in setting up a route from signal 14 to signal 17.

Signal controls.—When each of the track

switches has completed its operation in accordance with the positions required in setting up each proposed route, it has been pointed out that the relay LS associated with that track switch is dropped away to close the signal control circuits.

To consider an example of the signal control circuits provided for each of the signals in the track layout, assume the track switches 4TSA and 4TSB to have completed their operation to a locked reverse position in accordance with a route defined by an operator by the depression of an entrance button for signal 14 and an exit button for signal 17. When relay 4LS has been dropped away, a circuit is closed for relay 14G (see Fig. 3B) from (+), through a circuit including front contact 72 of relay 17XR, back contact 73 of relay 4LS, back contact 74 of relay 4NCR, front contact 75 of relay 4RCR, back contact 76 of relay 4NCR, back contact 77 of relay 4LS, back contact 78 of relay 14XR, front contact 79 of relay 14NR, and winding of relay 14G, to (-). The picking up of relay 14G applies energy at front contacts 80 and 81 to the search light signal mechanism of signal 14 to cause that signal to display a green clear indication.

The clearing of each signal causes the dropping away of its signal at stop repeater relay M, as, for example, the clearing of signal 15 causes the dropping away of relay 15M (see Fig. 2) when signal-at-stop contact 34 of signal 15 is opened.

Route and approach locking.—Inasmuch as the route locking used in this embodiment of the present invention is similar to that typically shown in prior applications, the route locking relays have been shown only in block form in the present disclosure (see Fig. 2). It is to be understood that the circuits by which those route locking relays are controlled are provided as typically shown, for example, in the prior application of Langdon, Ser. No. 175,466, filed November 26, 1937. It is also to be understood that other forms of route locking can as well be used, and that, if approach locking is required in practice, the route and approach locking can be provided as shown, for example, in the patent to C. F. Stoltz, Patent No. 2,115,511, dated April 26, 1938.

It is believed, however, that, for an understanding of the present invention, it is sufficient to consider that the relays ES and WS are respectively east and west directional stick normally energized relays, dropped away for the portion of each route occupied by, and in advance of, each train, and are energized as the passing train leaves the track section with which they are associated.

It is obvious, with reference to Fig. 2 of the accompanying drawings, that whenever either of the route locking relays associated with the detector track section for a particular track switch, are dropped away, the lock relay L for that track section is dropped away to cause the electric locking of that track switch to become effective.

Restoration to normal.—To consider how a signal can be restored to stop, and the parts of the system associated with the setting up of routes restored to normal at the will of an operator, assume, for example, an operator to cause the restoration of a route set up as heretofore described from signal 14 to signal 17 by pulling out button 14NB.

When button 14NB is pulled out, the stick

circuit for relay 14NR is opened at normally closed contact 35 of button 14NB to cause that relay to drop away. The dropping away of relay 14NR causes the dropping away of signal control relay 14G (see Fig. 3B) by opening the circuit for that relay at front contact 79, and the opening of front contacts 80 and 81 caused by the dropping away of relay 14G deenergizes the mechanism in signal 14 to cause that signal to be restored to the position to display a red stop indication.

The dropping away of relay 14NR also causes the dropping away of relay 17XR by opening the circuit for that relay at front contact 39. When relay 17XR is dropped away, the upper winding of relay 4R is deenergized, due to the opening of front contact 47 of relay 17XR. Inasmuch as the detector track section is unoccupied at that time, the center winding of relay 4R is deenergized, thus causing that relay to drop away.

A very similar mode of operation is effected upon passage of a train, the principal difference being that the stick circuit for relay 14NR is automatically opened as soon as a train accepts the entering signal 14, instead of being opened by the manual actuation of the entrance button 14NB. To consider an example of such restoration upon passage of a train, assume a route to be set up in a manner which has been described from signal 14 to signal 17, and assume an approaching train to accept signal 14 and enter track section 8.

When a train enters track section 8 and relay 8T is dropped away, under such conditions, the stick circuit for relay 14NR is opened at front contact 37 of relay 8T to cause relay 14NR to drop away and cause the restoration to normal of the relays associated with the route set up including that entrance point, and the restoration of signal 14 to stop, all in the same manner as described above, except that the restoration of relay 4R to normal is delayed until the passing train has left track sections 8 and 9.

Interlock between conflicting routes.—In an entrance-exit type system there is no locking or restraint of the manual actuation of the control buttons; and although the route locking forming a part of the system prevents actual power operation of switches in a route under or ahead of a train, even though the switch control relays to change the position of these switches might be energized, it is considered desirable that the operator should not be able by any manipulation of the control buttons to cause energization of any switch control relay to set up a route in conflict with the one occupied by a train. Among other things, such preconditioning of a switch in an occupied route for operation to a different position, when the train leaves and this switch is unlocked, is considered to be undesirable because it usually affords little, if any, additional facility in the movement of traffic, and adds the hazard that a switch so preconditioned might be improperly operated at some time under or ahead of a train in case of some failure of the route locking means, due to a momentary loss of track circuit shunt or the like. Accordingly, it is considered preferable to arrange the system so that a train must clear a route, with such sectional rear release features as may be expedient, before any manipulation of the control buttons is effective to set up any conflicting route.

As previously explained, the energization of a switch control relay for a given position of a

switch opens the initiating circuits for all routes over that switch in its other position; and consequently so long as this switch control relay is energized, the manipulation of control buttons 5 for any conflicting route is effective, since no operating potential is supplied to the exit relays for such routes. In order to maintain this same interlock between conflicting routes while a route is occupied by a train, as well as when this route 10 is set up by the route establishing means, provision is made in accordance with this invention to maintain the switch control relay for each switch in an occupied route energized until the train has passed out of the route, or at least out 15 of the detector track section for that switch.

A typical example of such control of the switch control relays is shown in Fig. 2 for the crossover 4. The middle windings of the switch control relays 4AN, 4BN, and 4R for this crossover 20 4 are provided with stick circuits closed when the lock relays 8L and 9L associated with this crossover are deenergized. It is contemplated that the lock relays for the various switches, such as the lock relays 8L and 9L for the crossover 4, 25 will be controlled by route locking means, preferably with sectional rear release in accordance with regular practice and in the manner disclosed more in detail in our prior specification No. 477,671, so that the lock relays for each 30 switch in a route are deenergized when the entrance signal clears and is maintained deenergized ahead of a train traversing the route until that train has passed out of the corresponding detector track section. Although the simple 35 track layout shown in Fig. 2 does not include enough switches or crossovers to take advantage of the rear release features afforded by the use of directional stick relays in this type of route locking, the way in which the lock relays are intended to be controlled by such directional stick 40 relays is illustrated in Fig. 2 for the crossover 4; and from this example it can be readily understood how the desired interlock between conflicting routes is maintained with such facility of sectional rear release that the track layout may afford. 45

As a typical example of the contemplated operation, assume that the switch control relay 4R is energized to establish a route over the crossover 4 in the reverse position from signal 14 to signal 17 in the manner above explained. When the signal 14 assumes its clear condition, the directional stick relays 8ES and 9ES for east-bound train movement are automatically deenergized, opening at their front contacts 221 and 223 the circuits for the lock relays 8L and 9L respectively. This deenergization of the lock relay 8L closes a stick circuit for the switch control relay 4R which may be traced from (+), 50 through the back contact 85 of this relay 8L, front contact 86 of relay 4R, back contact 87 of relay 4AN, middle winding of relay 4R, and back contact 88 of relay 4BN, to (-). Similarly, the deenergization of the lock relay 9L closes 55 another stick circuit for the relay 4R, which may be traced from (+), through the back contact 89 of relay 9L, front contact 90 of relay 4R, back contact 87 of relay 4AN, middle winding of relay 4AN, and back contact 88 of relay 4BN, to (-). In this way the switch control relay 60 for the position of each switch included in a route is held up by a stick circuit as soon as the signal clears for train movement into the route.

In the example assumed, when a train leaves 75 the track section 8 and the signal 14 assumes

its stop condition, the directional stick relays 8ES and 9ES are maintained deenergized in accordance with the mode of operation characteristic of this form of route locking, thereby keeping the lock relays 8L and 9L deenergized and 5 the switch control relay 4R energized, although the entrance of this train automatically restores the entrance relay 14NR in the manner previously explained, thereby deenergizing the exit relay 17XR and the completion circuit for energizing the switch control relay 4R. In this way, 10 the switch control relays of switches in an occupied route are kept energized to maintain the interlocking between conflicting routes after the route establishing means has been restored to 15 normal.

In the case assumed, when the train leaves the track section 8 but is still in the track section 9, the lock relay 8L may pick up, but since both ends of the crossover 4 are assumed to be operated 20 from the same switch machine, and the presence of a train in the track section 9 should prevent operation of this crossover, the switch control relay 4R is still held up by the lock relay 8L until the train also clears the track section 9. In the 25 case of a more complicated track layout, however, where the rear release of switches by the picking up of directional stick relays in the rear of a train is available, the energization of a lock relay in this manner, and the resultant release 30 of the associated switch control relay, can close initiating circuits for routes over a switch in a different position before the train has entirely cleared the route.

If, in the example assumed, the train should 35 move in the opposite direction over the route from signal 17 to signal 14, the directional stick relays 8WS and 9WS for the other direction are operated in the same manner to control the energization of relay 4R; and it can be seen that 40 the control of the switch control relays in this manner acts to maintain the interlocking between conflicting routes for both directions of traffic.

End-to-end or through route control.—To provide that an operator need only actuate the control buttons for the extreme ends of each route to be set up, irrespective of the number of intermediate signals included in that complete route, a system is provided whereby the route initiated 50 is selected by sections in a successive order, a section being provided for each interlocked group, starting with the section for the interlocked group nearest the exit point.

To consider the general mode of operation of 55 the system in setting up routes by end-to-end control, assume, for example, an operator to initiate the setting up of a route from signal 16 to signal 11, at a time when the normal conditions of the system exist as illustrated and here- 60 tofore described.

In setting up a route from signal 16 to signal 11, relay 16NR (see Fig. 1F) is picked up when the entrance button 16NB is depressed, and the picking up of relay 16NR applies energy to the initiating network in such a manner as to feed toward the exit relays for all available exit points for routes having an entrance point at signal 16. The picking up of relay 16NR causes the energization of relay 4AY, the picking up of which 70 closes a portion of the selecting network circuit for completing a circuit through to the exit relay for each available exit point. Although the general mode of operation of the system is to pick up a route selector relay Y for each track switch 75

trailed for main line traffic for the particular route set up, the route selector relay 3AY is controlled in a different manner for purposes to be hereinafter pointed out in considering the selection of optional routes. Inasmuch as relay 3AY is not picked up in setting up a route from signal 16 to signal 11, the initiating network circuit for each available exit relay XR can be completed after relay 4AY has picked up. Thus, an operator proceeds to designate the exit point for the proposed route by the depression of button 11XB, and relay 11XR is picked up as a result of such actuation.

When relay 11XR is picked up, in setting up such a route, relay 2R is energized because it is selected in preference to relay 2BN by the dropped away position of the route selector relay 2BY, and the picking up of relay 2R causes the energization of relay 3AN in preference to relay 3R because the route selector relay 3AY is dropped away. After relay 3AN is picked up, relay 12XP is energized, and the picking up of that relay effects the energization in turn of relay 12NR and 14XR respectively. Upon the picking up of relay 14XR, relay 12XP is deenergized and allowed to drop away, after completing its principal purpose of causing the picking up of the entrance relay associated with signal 12, and after causing the picking up of the next exit relay 14XR. When relay 14XR is picked up, relay 4AN is energized in preference to relay 4R because the route selector relay 4AY is already picked up to select that particular relay.

Thus, the switch control relays in the completion network are positioned for the entire route designated, and the track switches with which those relays are associated are positioned in a manner similar to that which has been heretofore described as typical for the track switches associated with crossover 4ts. After the track switches have completed their operation to positions required for such a route, the signals for each of the interlocked groups provided for governing traffic through that route are cleared, each signal being energized by circuits provided for that particular interlocked group in a manner which has been heretofore described as typical of all signal control circuits.

Having thus considered the general mode of operation in setting up a route by end-to-end control, consideration will now be given to the details of the circuits which provide such mode of operation, it being assumed that the normal conditions of the system exist as heretofore described, and that an operator proceeds to set up a route as heretofore described in a general manner from signal 16 to signal 11.

The actuation of button 16NB in setting up such a route, causes the picking up of relay 16NR (see Fig. 1F) by the energization of a circuit closed from (+), through a circuit including, contact 91 of button 16NB closed in a depressed position, front contact 92 of relay 8T, and winding of relay 16NR, to (-). The picking up of relay 16NR closes a stick circuit for that relay from (+), through a circuit including contact 91 of button 16NB closed when button 16NB is both normal and depressed, from contact 93 of relay 16NR, front contact 92 of relay 8T, and winding of relay 16NR, to (-). Back contact 215 of relay 8TP is connected in multiple with front contact 92 of relay 8T to provide that relay 16NR can be picked up when track section 8 is occupied as well as when it is unoccupied.

Upon the picking up of relay 16NR a circuit

is closed to cause the picking up of relay 4AY by the energization of a circuit closed from (+), through a circuit including front contact 94 of relay 16NR, back contact 95 of relay 16XR, back contact 96 of relay 4R, and winding of relay 4AY, to (-).

When an operator designates the exit point for the route being set up, by the depression of button 11XB, a circuit is closed for relay 11XR, from (+), through a circuit including front contact 94 of relay 16NR, back contact 95 of relay 16XR, back contact 96 of relay 4R, front contact 97 of relay 4AY, back contact 98 of relay 14XR, front contact 99 of relay 4NCR and front contact 100 of relay 9T connected in multiple, front contact 101 of relay 8T, wire 182, front contact 103 of relay 12M, back contact 104 of relay 12NR, back contact 105 of relay 12XR, back contact 106 of relay 3R, back contact 107 of relay 3AY, wire 108, back contact 109 of relay 2BN, back contact 110 of relay 2AN, back contact 111 of relay 2BY, winding of relay 11XR, back contact 112 of relay 11NR, and contact 113 of button 11XB closed in a depressed position, to (-). Upon the picking up of relay 11XR, a stick circuit is closed for that relay at front contact 114 to shunt out, in the circuit above described, contacts 112 of relay 11NR and 113 of button 11XB.

Upon the picking up of relay 11XR, relay 2R is picked up when its circuit is energized from (+), through a circuit including front contact 115 of relay 11XR, back contact 116 of relay 2BY, lower winding of relay 2R, back contact 117 of relay 2BN, and back contact 118 of relay 2AN, to (-). When relay 2R is picked up, a circuit is closed to cause the picking up of relay 3AN, from (+), through a circuit including front contact 115 of relay 11XR, back contact 116 of relay 2BY, front contact 119 of relay 2R, wire 120, back contact 121 of relay 3AY, lower winding of relay 3AN, and back contact 122 of relay 3R, to (-).

A circuit is closed upon the picking up of relay 3AN for the energization of relay 12XP, from (+), through a circuit including front contact 115 of relay 11XR (see Fig. 1D), back contact 116 of relay 2BY, front contact 119 of relay 2R, wire 120, back contact 121 of relay 2AY, front contact 123 of relay 3AY, winding of relay 12XP, and back contact 124 of relay 12NR, to (-). When relay 12XP is picked up, a stick circuit is closed for that relay to shunt back contact 124 of relay 12XR out of the circuit just described by a circuit closed from wire 125, through a circuit including front contact 126 of relay 12XP, wire 127, and back contact 128 of relay 14XR, to (-).

A circuit is closed upon the picking up of relay 12XP for relay 12NR, from (+), through a circuit including normally closed contact 129 of button 12NB, front contact 130 of relay 12XP, wire 131, back contact 132 of relay 14NR, wire 133, front contact 134 of relay 6T, and winding of relay 12NR, to (-). A stick circuit is closed for relay 12NR upon the picking up of that relay from (+), through a circuit including normally closed contact 129 of button 12NB, front contact 135 of relay 12NR, wire 131, back contact 132 of relay 14NR, wire 133, front contact 134 of relay 6T, and winding of relay 12NR, to (-).

Back contact 216 of relay 6T is connected in multiple with front contact 134 of relay 6T to provide that relay 12NR can be picked up when track section 8 is occupied as well as when it is unoccupied.

The initiating circuit by which relay 11XR is maintained energized, is maintained closed dur- 75

ing the shifting of contact 104 of relay 12NR by front contact 217 of relay 12XP connected in multiple with back contact 104. The picking up of relay 12NR applies energy to the initiating network for energization of relay 11XR at front contact 104 the same as is done in setting up a route within that interlocked group.

Upon the picking up of relay 12NR, a circuit is closed for relay 14XR from (+), through a circuit including front contact 94 of relay 16NR (see Fig. 1F), back contact 95 of relay 16XR, back contact 96 of relay 4R, front contact 97 of relay 4AY, winding of relay 14XR, back contact 136 of relay 14NR, wire 137, back contact 138 of relay 12XR, front contact 139 of relay 12NR, and front contact 140 of relay 12XP, to (-). The picking up of relay 14XR, due to such energization, closes a stick circuit for that relay from (+), through a circuit including front contact 94 of relay 16NR (see Fig. 1F), back contact 95 of relay 16XR, back contact 96 of relay 4R, front contact 97 of relay 4AY, winding of relay 14XR, and front contact 141 of relay 14XR, to (-).

The picking up of relay 14XR causes the dropping away of relay 12XP by opening the stick circuit for that relay at back contact 128 (see Fig. 1F), the pick-up circuit for that relay having been opened upon the picking up of relay 12NR at back contact 124 (see Fig. 1E).

When relay 14XR is picked up in setting up a route from signal 16 to signal 11, relay 4AN is picked up by the energization of a circuit closed from (+), through a circuit including front contact 142 of relay 14XR (see Fig. 1F), front contact 143 of relay 4AY, lower winding of relay 4AN, and back contact 54 of relay 4R, to (-).

Thus, the circuits have been completely described by which the self-selecting network is positioned in setting up a route by end-to-end control, and it is believed that it can be readily understood by those familiar with the art how the track switches are positioned and the signals are cleared for the route being set up in a manner which has been heretofore typically illustrated and described.

With the end-to-end system described above as typical, it will be readily apparent to those familiar with the art how the system can be applied to any particular track layout in accordance with the requirements of practice, and how the end-to-end system of control can be extended through as many interlocked groups as desired.

Through route initiating circuit conditions.— In connection with this through route operation just explained, the through route connection for the initiating circuits of adjoining interlocked groups permit the functions of the initiating circuits to be performed for a plurality of interlocked groups, including the preselection of the position of trailede switches in different interlocked groups to conform with the routes or portions thereof available, and the automatic selection of alternative or optional through routes; and in order that these preselecting or initiating functions may not create improper operating conditions, these through route connections have to be broken under certain conditions, which may be considered at this time.

In the first place, when an intermediate signal is an exit end of an established route, the corresponding through route connection is broken to wipe out any energization of the initiating circuits for the adjoining interlocked group which

would interfere with the setting up of any desired route through that adjoining route. Accordingly, the through route connection for each intermediate signal includes back contacts of the corresponding exit relays. Considering for example the through route connection just described at the intermediate signals 12 and 14 for the west-bound initiating circuits, it will be noted that this connection includes a back contact 98 of the exit relay 14XR and a back contact 105 of the exit relay 12XR, so that whenever the signal 14 or signal 12 is made the exit end of a route established over a corresponding interlocked group, this through route connection is broken. Also, if the intermediate signal 12 has been made the entrance end of some established route by energization of the entrance relay 12NR, the corresponding through route connection to the adjoining interlocked group in the rear is broken at the back contact 104 of this entrance relay, so that the energization of initiating circuits of said adjoining interlocked group for any reason cannot act to maintain energization of the through route establishing means for said established route independently of said entrance relay, and thus interfere with the proper operation of the system.

Another feature of the desired control of the through route connections is exemplified by the contacts 100 and 101 of the track relays 8T and 9T in the particular through route connection under consideration. It can be seen that there are two routes connecting with the intermediate signal 14, one between this signal 14 and the signal 16 over the crossover 4 in the normal position, and the other between the signal 14 and the signal 17 over the crossover 4 in the reverse position. Referring to Fig. 2, the track relay 8 relates to the upper track and is deenergized if a train occupies any part of the first route above mentioned. Similarly, the track relay 9T relates to the lower track, and a train in any part of the other route over the crossover 4 in the reverse position will deenergize either track relay 8T or the track relay 9T. Consequently, when either one of these routes is occupied by a train, regardless of its direction of movement in entering the route, the contacts 100 and 101 of the track relays 8T and 9T break the through route connection for the signal 14. The contact 99 of the relay 4NCR, energized when the crossover 4 is in its normal position, provides a shunt for the contact 100 of the track relay 8T, and thus eliminates the control of the through route connection by this track relay 9T when the route along the upper track over the cross-over 4 in the normal position is the one established, so that a train on the lower track will not break the through route connection for the signal 12 and interfere with the establishing of a non-conflicting through route along the upper track between signal 16 and either signal 10 or signal 11. A similar arrangement of track relay contacts selectively included in the through route connections in accordance with the switches is employed for the other through route connections in the same way; and the initiating circuits of one interlocked group are disconnected from those in the adjoining interlocked group with respect to each intermediate signal location when a train is present in a route extending to that signal location.

To illustrate the purpose of this track circuit control of through route connections, assume that a route is established between signal 16 and 14 and a train has entered this route, and sup-

pose that, while this train is present in the track section 8, the operator actuates the entrance button 16NB to set up a route for a train approaching the signal 16. The entrance relay 5 16NR is energized under these conditions, even with the train present in the track section 8, because its energizing circuit includes the back contact 215 of the track relay repeater 8TP. If the operator should actuate the exit button 14XB, a 10 route from the signal 16 to the signal 14 will be established in the usual way for the approaching train to enter the occupied route, for the purpose of coupling or uncoupling the cars for example. If, however, the operator should actuate 15 exit buttons for the signals 10 or 11, either carelessly or accidentally, or perhaps for some through route that the track layout might afford for train movement around the train in the track section 8, although not shown in the 20 particular track layout illustrated, the through route connection for the signal 14 is open at the front contact 101 of the track relay 8T. Consequently, there can be no energization of the 25 initiating circuits for the adjoining interlocked group to establish a route connecting with the signal 14 and thus cause signal 12 to clear for the train in the track section 8, contrary to the intentions of the operator, or interfere with the establishing of some through route around this 30 train if afforded by the track layout and otherwise available.

In case a route is set up between the signals 17 and 18 over the crossover 4 in the reverse position, and a train has entered this route, the 35 operator can actuate the entrance button 17NB and the exit button 14XB to set up the same route for a following train, but he cannot set up any through route by actuation of the entrance button 17NB with either the exit button 10XB 40 or 11XR. Under these conditions, the through route connection for signal 14 is broken at the contact 100 of the track relay 9T, or the contact 101 of the track relay 8T, as the case may be, contact 99 of relay 4NCR being opened because 45 the crossover 4 is in the reverse position. Likewise, no current is supplied to the through route connections for the signal 15, since a route between signals 17 and 15 conflicts with the established route between signals 17 and 14, and 50 the initiating circuit to supply operating potential to the exit relay 15XR and to the through route connection at signal 15 from the front contact 144 of the entrance relay 17NR is open at the back contact 146 of the switch control 55 relay 4R, which is maintained energized by its stick circuit with the train present in the manner previously explained.

In this way, the through route connections are controlled by the presence of trains so that an 60 operator cannot set up a through route including a section occupied by a train, regardless of the direction of movement of that train when it entered that section, it being evident that the contacts of the track relays are open irrespective of the direction of movement of the train.

Considering another feature of control of the through route connections, when a through route has been established and a train passes an intermediate signal, the corresponding entrance relay is automatically deenergized to cause that signal to indicate stop and also deenergize the exit relay and completion circuits for the route then established. To insure effective deenergization and release of the exit stick relay when 75 the entrance relay is thus automatically re-

stored, the corresponding through route connection is maintained open by the action of a signal repeater relay M long enough for the exit relay to drop, and thereby avoid any improper maintained energization of the exit relay in the event 5 that the initiating circuits for the adjoining interlocked groups should happen to be energized by the actuation of an entrance button at the time the entrance relay is automatically restored.

For example, assume a route to be set up as heretofore described from signal 16 to signal 11, and assume a train to have entered track section 8 to cause the restoration to normal of signal 16 and the parts of the self-selecting network 15 associated with setting up a route from signal 16 to signal 11. Also, assume that an operator actuates button 16NB to cause the picking up of relay 16NR for setting up a proposed route, at that time, but fails to designate an exit point 20 for such a route. The picking up of relay 16NR feeds energy through the self-selecting network toward the exit relays 14XR, 10XR and 11XR, but that branch of the self-selecting network circuit is open at front contact 103 of relay 12M. 25 Assume the passing train to accept signal 12 and enter track section 6 to cause the dropping away of relay 12NR. As a result of the dropping away of relay 12NR, the circuit heretofore described for relay 11XR is opened at front contact 104, 30 and that relay is allowed sufficient time to drop away because its circuits as heretofore described as extending through the initiating network for end-to-end control from relay 16NR is opened at front contact 103 of relay 12M. It has been 35 pointed out that relay 12M is a signal-at-stop repeater relay, and that the signal is restored to stop as a result of the dropping away of the relay NR associated with that signal. Thus, relay 12NR in dropping away causes the dropping 40 away of the signal control relay 12G (see Fig. 3A), the dropping away of relay 12G causes the restoration of signal 12 to stop, and the restoration of signal 12 to stop causes the energization of relay 12M. It is apparent that sufficient 45 time is provided between the time when the circuit for relay 11XR is opened at front contact 104 of relay 12NR, and between the time the stick circuit for that relay is closed at front contact 103 of relay 12M to provide that relay 50 11XR will have time to drop away. This feature of the end-to-end system for control, provides that an operator must always designate by actuation of control buttons for both the entrance and exit ends of each route, each route to be set up. 55

It is believed readily apparent from the drawings that a signal repeater relay M is included in the end-to-end control of the initiating network for each intermediate signal included in the track layout for the purpose above set forth. 60

Preferred route selection.—It has been heretofore pointed out in a general manner what conditions are encountered in practice in connection with the selection of a preferred route of a plurality of optional routes, and the means provided 65 by the self-selecting network for selecting a particular preferred route. A means has been pointed out in the above mentioned prior Langdon applications Ser. No. 119,641, filed January 8, 1937, and Ser. No. 176,466, filed November 26, 1937, 70 whereby, of several optional routes available, the route diverging nearest the entrance point is always given preference. Consideration is now given more in detail to the means provided by this invention whereby any particular route can 75

be given preference over a plurality of optional routes available, irrespective of whether or not it diverges nearest the entrance or exit point.

Thus, it has been provided in the present embodiment of this invention that a route set up 5 from signal 17 to signal 10 is set up via crossover 3ts in preference to the inferior optional route via crossover 4ts. Such preference is accomplished by the control circuit for the route 10 selector relay 3AY (see Fig. 1E) associated with track switch 3TSA.

To consider the general mode of operation of the system by which the route from signal 17 to signal 10 via crossover 3ts is made preferred, the 15 initiating network circuits can be considered to assume a form similar in effect to the actual track layout for which the system is provided. That is, the network system feeds energy, when an entrance point is designated, for example, at signal 17, at a time when the heretofore described 20 normal conditions of the system exist, through the initiating network circuits toward the exit relay for each available exit point. Thus, energy can be said to feed in directions corresponding to 25 traffic through the actual track layout in the field from entrance relay 17NR through a normal branch of the network circuits associated with crossover 4ts to relay 15XR, and through a branch of the network corresponding with the 30 crossover 3ts having its track switches 3TSA and 3TSB in a reverse position to exit relay 10XB. There is also a multiple path, as there is in the 35 track layout from relay 17NB through a branch of the initiating network corresponding to crossover 4ts with its track switches 4TSA and 4TSB in reverse positions to exit relay 14XB, and through a branch of the self-selecting network corresponding with the normal position of the 40 track switches associated with crossover 3ts to exit relay 10XB.

The route selector relays Y, as has been heretofore pointed out, are connected in multiple in the initiating network at various points where 45 selections are included for the track switches with which those relays are associated. Thus, a relay 4AY (see Fig. 1F) is provided in the initiating network in the normal branch of the network extending from a front contact of relay 16NB; and when relay 4AY is dropped away, the 50 reverse branch of the self-selecting network is closed from a front contact of entrance relay 17NB over the reverse branch of the initiating network circuits corresponding with crossover 4ts with its track switches in the reverse position, and when relay 4AY is picked up, that 55 reverse branch of the circuit is opened, and the normal branch of the circuit extending from a front contact of entrance relay 16NB, to exit relay 14XB, is closed.

60 The relay 3AY (see Fig. 1E), associated with track switch 3TSA, however, is energized from the branch of the initiating network corresponding with crossover 3ts having its track switches in a reverse position. When relay 3AY is 65 dropped away, the circuits through the self-selecting network are closed through the normal branch corresponding with the track including track switch 3TSA in a normal position, and when that relay is picked up, the initiating network circuits for setting up routes for west 70 bound traffic are closed through a branch of the circuit corresponding to crossover 3ts having its track switches in reverse positions. It is thus provided that, in setting up a route from signal 75 17 to signal 10, the branch of the initiating cir-

cuit network is closed corresponding to the route between those designated entrance and exit points via crossover 3ts in a reverse position because relay 3AY becomes energized, and the branch of the initiating network corresponding to the route designated between signal 17 and signal 10 via crossover 4ts in a reverse position is opened upon the picking up of this relay 3AY. 5

Such mode of operation renders the portion of the self-selecting network corresponding with the route diverging nearest the entrance point ineffective for setting up such a route, and gives preference to the particular route for which the route selector relay Y is energized in the reverse branch of the initiating network control. 15

To consider details of the mode of operation by which the route from signal 17 to signal 10 via crossover 3ts is given preference over other routes, assume an operator to depress button 17NB at a time when the normal conditions of 20 the system exist as heretofore described. As a result of such actuation relay 17NR (see Fig. 1F) is energized by circuits closed in a manner similar to that described associated with the circuits for relay 16NR as typical, and the picking up of relay 17NR provides energy for relay 3AY by a circuit closed from (+), through a circuit including front contact 144 of relay 17NR, back contact 145 of relay 15XR, back contact 146 of relay 4R, back contact 147 of relay 15XR, 30 front contact 148 of relay 9T, wire 149, front contact 150 of relay 12M, back contact 151 of relay 13NR, back contact 152 of relay 13XR, back contact 153 of relay 3BN, back contact 154 of relay 3AN, and winding of relay 3AY, to (-). 35 The picking up of relay 3AY, opens the normal branch of the initiating network circuit at back contact 107.

Upon designation of the exit point for the 40 route being set up, by the depression of button 10XB, an operator causes the picking up of relay 10XR (see Fig. 1D) by the energization of a circuit closed from (+), through a circuit including front contact 144 of relay 11NR (see Fig. 1F), back contact 145 of relay 11XR, back 45 contact 146 of relay 4R, back contact 147 of relay 15XR, front contact 148 of relay 9T, wire 149, front contact 150 of relay 13M, back contact 151 of relay 13NR, back contact 152 of relay 13XR, back contact 153 of relay 3BN, back 50 contact 154 of relay 3AN, front contact 107 of relay 3AY, wire 108, back contact 155 of relay 2R, winding of relay 10XR, back contact 156 of relay 10NR, and contact 157 of button 10XB closed in a depressed position, to (-). The 55 picking up of relay 10XR closes a circuit at front contact 158 to shunt contacts 157 and 156 out of the circuit heretofore described.

Upon the picking up of relay 10XR, a circuit 60 is closed for the energization of relay 2AN, from (+), through a circuit including front contact 159 of relay 10XR, lower winding of relay 2AN, and back contact 160 of relay 2R, to (-). When relay 2AN is picked up, a circuit is closed to cause the picking up of relay 3R from (+), 65 through a circuit including front contact 159 of relay 10XR (see Fig. 1D), front contact 161 of relay 2AN, wire 120, front contact 121 of relay 3AY, lower winding of relay 3R, back contact 162 of relay 3BN, and back contact 163 of relay 3AN, to (-). 70

When relay 3R is picked up, a circuit is closed for the energization of relay 13XP from (+), through a circuit including front contact 159 of relay 10XR (see Fig. 1D), front contact 161 of 75

- relay 2AN, wire 120, front contact 121 of relay 3AY, front contact 164 of relay 3R, winding of relay 13XP, and back contact 165 of relay 13NR, to (-). Upon the picking up of that 5 relay a stick circuit is closed to maintain that relay energized until relay 15XR is picked up, from (+), through a circuit including front contact 159 of relay 10XR, front contact 161 of relay 2AN, wire 120, front contact 121 of relay 10 3AY, front contact 164 of relay 3R, winding of relay 13XP, front contact 166 of relay 13XP, wire 167, and back contact 168 of relay 15XR, to (-). A circuit is closed for the energization of relay 15 13NR (see Fig. 1E), upon the picking up of relay 13XP, from (+), through a circuit including contact 169 of button 13NB closed in a normal position, front contact 170 of relay 13XP, wire 171, back contact 172 of relay 15NR, wire 173, front contact 174 of relay 7T, and winding 20 of relay 13NR, to (-). When relay 13NR is picked up, a stick circuit is closed for that relay the same as just described except that front contact 175 of relay 13NR is closed to shunt front contact 170 of relay 13XP out of the circuit. 25
- The initiating circuit by which relay 10XR is maintained energized, is maintained closed during the shifting of contact 151 of relay 13NR (see Fig. 1D) by front contact 218 of relay 13XP 30 connected in multiple with contact 151. The picking up of relay 13NR applies energy to the initiating network for energizing relay 10XR at front contact 151 the same as is done in setting up a route within an interlocked group. 35
- After relay 13NR is picked up, a circuit is closed for the energization of relay 15XR, from (+), through a circuit including front contact 144 of relay 17NR (see Fig. 1F), back contact 145 of relay 17XR, back contact 146 of relay 4R, 40 winding of relay 15XR, back contact 175 of relay 15NR, wire 176, back contact 177 of relay 13XR, front contact 178 of relay 13NR, and front contact 179 of relay 13XP, to (-). When relay 15XR is picked up, the above described 45 stick circuit for relay 13XP is opened at back contact 168 to cause relay 13XP to drop away. A stick circuit is closed, upon the picking up of relay 15XR at front contact 219 of relay 15XR, from (+), through a circuit including front contact 144 of relay 17NR, back contact 145 of relay 17XR, back contact 146 of relay 4R, winding of relay 15XR, and front contact 219 of relay 15XR, to (-). Upon the picking up of relay 15XR, under 55 such conditions, relay 4BN is picked up by the energization of a circuit closed from (+), through a circuit including front contact 180 of relay 15XR, lower winding of relay 4BN, and back contact 54 of relay 4R, to (-). 60
- Responsive to the picking up of relays 2AN and 4BN, the track switches associated with crossovers 2ts and 4ts are operated to their normal positions, and responsive to the picking up of relay 3R, the track switches associated with 65 crossover 3ts are operated to their reverse positions, all in a manner similar to the condition described as typical of the system when considering the details of the switch control circuits. 70
- After the track switches have assumed their selected positions, the signals are cleared as a result of the energization of circuits similar to a signal control circuit heretofore described as typical of the circuits provided for clearing each of the signals. 75
- It is therefore readily apparent that, in order

to give a route via a particular track switch preference over optional routes, irrespective of the location of the track switches in the route, the Y relay energized for that particular track switch or crossover for that particular direction of traffic is energized in the reverse control branch of the initiating network, and the reverse switch control relay for controlling that track switch is selected for energization when the Y relay is picked up. 10

In view of the nature of the means provided for causing a particular route to be preferred, the same system can be used to select the preferred or superior route to be established within an interlocked group, as for example, if the 15 crossovers 3 and 4 in the same parallel relation shown were included in the same interlocked group instead of different interlocked groups as illustrated. By arranging the route selector relay 3AY for the crossover 3 in the reverse branch of the initiating circuits, the optional route over the crossover 3 in the reverse position would be normally established for west-bound traffic, and with the relay 4BY for the crossover 4 included in the normal branch of the initiating 25 circuits as illustrated, the optional route over the same crossover 3 in the reverse position would also be normally established for east-bound traffic. In other words, the same crossover 3 in the reverse position would be used for the preferred 30 or superior optional route for both directions of train movement. This arrangement can be employed if one crossover 3 is better equipped for high speed train movement than the other crossover 4, or where it may be desirable to cause 35 trains for both directions of movement to use the same portion of track to stop at a platform or the like.

Another arrangement for obtaining a similar selection of the preferred optional route involves 40 an auxiliary or special selector relay 3YY (see Fig. 1B), which is associated with the crossover 3 to open the reverse branch of the initiating circuit network under normal conditions, so that upon energization of the entrance relay 10NR 45 for the common entrance end of the optional routes illustrated, no current is supplied by the initiating circuits to energize the route selector 4BY to preselect the normal position of the crossover 4 in preference to its reverse position. This 50 causes the route to be set up by the completion circuits over the crossover 4 in the reverse position, and thus gives a different optional route than would otherwise exist without the control 55 exercised by the auxiliary selector relay 3YY. 55

To consider the details of the circuits which provide the mode of operation generally outlined above, assume the system to be under the normal conditions heretofore described, and assume an operator to proceed to set up a route from 60 signal 10 to signal 11, by actuating the control buttons corresponding with those entrance and exit points respectively. The depression of button 10NB causes the picking up of relay 10NR by the energization of a circuit similar to the 65 circuit heretofore described as typical for the energization of relay 16NR.

Upon the picking up of relay 10NR in setting up that particular route, a circuit is closed for the energization of relay 2AY (see Fig. 1A), from 70 (+), through a circuit including front contact 181 of relay 10NR, back contact 182 of relay 10XR, back contact 183 of relay 2R, and winding of relay 2AY, to (-). After relay 2AY is picked up, and after an operator has depressed 75

the exit button 17XB for the proposed route, a circuit is closed to cause the picking up of relay 17XR (see Fig. 1C) from (+), through a circuit including front contact 181 of relay 10NR (see Fig. 1A), back contact 182 of relay 10XR, back contact 183 of relay 2R, front contact 184 of relay 2AY, wire 196, back contact 185 of relay 3R, back contact 186 of relay 12XR, front contact 187 of relay 7T and front contact 188 of relay 2NCR connected in multiple, front contact 189 of relay 6T, wire 190, front contact 191 of relay 14M, back contact 192 of relay 14NR, back contact 193 of relay 14XR, back contact 41 of relay 4AN, back contact 42 of relay 4BN, back contact 43 of relay 4BY, winding of relay 17XR, back contact 44 of relay 17NR, and contact 45 of button 17XB closed in a depressed position, to (-). A stick circuit is closed upon the picking up of relay 17XR at front contact 46 to shunt contacts 44 and 45 out of the circuit just described.

Upon the picking up of relay 17XR a circuit is closed for the energization of relay 4R (see Fig. 1F), from (+), through a circuit including front contact 47 of relay 17XR, back contact 48 of relay 4BY, upper winding of relay 4R, back contact 49 of relay 4BN, and back contact 50 of relay 4AN, to (-). The picking up of relay 4R effects the picking up in turn of relays 14XP, 14NR and 12XR in a similar manner to that heretofore described in considering the mode of operation of the system in setting up routes by end-to-end control.

Upon the picking up of relay 17XR, in setting up that route, relay 3AN (see Fig. 1E) is picked up by the energization of a circuit closed from (+), through a circuit including front contact 192 of relay 12XR, upper winding of relay 3AN, and back contact 192 of relay 3R, to (-). The picking up of relay 3AN causes the picking up of relay 2AN by the energization of a circuit closed from (+), through a circuit including front contact 192 of relay 12XR, front contact 193 of relay 3AN, wire 194, front contact 195 of relay 2AY, upper winding of relay 2AN, and back contact 190 of relay 2R, to (-).

In response to the picking up of the completion network relays in setting up such a route, the track switches are operated to their proper positions, and the proper signals are cleared by the energization of circuits similar to those heretofore described as typical of the system.

If, however, in setting up a route from signal 10 to signal 17, the route is not available via crossover 4ts, but it is available via crossover 3ts, the available route is set up. Such a condition can exist when a train is in track section 3 in going from signal 14 to signal 16 or from signal 16 to signal 14; when a route is set up from signal 14 to signal 16 or from signal 16 to signal 14; or when the auxiliary switch control lever for governing the track switches associated with crossover 4ts is operated to a normal control position. In each case, the normal switch control relay 4AN is picked up, and the picking up of that relay opens the heretofore described normally energized circuit for relay 3YY at back contact 20 (see Fig. 1C) to cause that relay to drop away and close the reverse branch of the initiating circuits associated with crossover 3ts.

To consider the details of the circuits involved in setting up the inferior route from signal 10 to signal 17, assume any of the above described conditions to exist in which relay 4AN is picked up to cause the dropping away of relay 3YY, and

assume the system otherwise to be in the heretofore described normal conditions.

The actuation of the entrance button 10NB for designation of the entrance point for the setting up of a route, under such conditions, causes the picking up of relay 10NR by the energization of a circuit similar to that described for relay 16NR as typical. The picking up of relay 10NR causes the picking up of relay 2AY by the energization of a circuit heretofore described. 10

After relay 2AY is picked up, a circuit is closed for relay 4BY (see Fig. 1C), extending from (+), through a circuit including front contact 181 of relay 10NR (see Fig. 1A), back contact 182 of relay 10XR, back contact 183 of relay 2R, front contact 184 of relay 2AY, wire 196, back contact 197 of relay 3YY, back contact 198 of relay 3AN, back contact 199 of relay 3BN, back contact 200 of relay 3BY, back contact 201 of relay 13XR, front contact 202 of relay 7T, front contact 203 of relay 6T and front contact 204 of relay 3NCR connected in multiple, wire 205, front contact 206 of relay 15M, back contact 51 of relay 15NR, back contact 52 of relay 15XR, back contact 53 of relay 4R, and winding of relay 4BY, to (-).

The actuation of the button 17XB for the exit point in the route to be set up closes a circuit for the energization of relay 17XR (see Fig. 1C) extending from (+), through a circuit including front contact 181 of relay 10NR (see Fig. 1A), back contact 182 of relay 10XR, back contact 183 of relay 2R, front contact 184 of relay 2AY, wire 196, back contact 197 of relay 3YY, back contact 198 of relay 3AN, back contact 199 of relay 3BN, back contact 200 of relay 3BY, back contact 201 of relay 13XR, front contact 202 of relay 7T, front contact 203 of relay 6T and front contact 204 of relay 3NCR connected in multiple, wire 205, front contact 206 of relay 15M, back contact 51 of relay 15NR, back contact 52 of relay 15XR, back contact 53 of relay 4R, front contact 43 of relay 4BY, winding of relay 17XR, back contact 44 of relay 17NR, and contact 45 of button 17XB, closed in a depressed position, to (-). A stick circuit is closed upon the picking up of relay 17XR at front contact 46 to shunt contacts 44 and 45 out of the circuit just described.

The picking up of relay 17XR causes the picking up of relay 4BN (see Fig. 1F) by the energization of a circuit heretofore described, and the picking up of relay 4BN causes the energization in turn of relays 15XP, 15NR (see Fig. 1C) and 13XR (see Fig. 1B) in a manner similar to that heretofore described in considering the details of the end-to-end system for control. 55

Upon the picking up of relay 13XR, relay 3R (see Fig. 1E) is picked up by the energization of a circuit closed from (+), through a circuit including front contact 207 of relay 13XR, back contact 208 of relay 3BY, upper winding of relay 3R, back contact 162 of relay 3BN, and back contact 163 of relay 3AN, to (-). Upon the picking up of relay 3R, relay 2AN (see Fig. 1D) is picked up by the energization of a circuit closed from (+), through a circuit including front contact 201 of relay 13XR (see Fig. 1E), back contact 208 of relay 3BY, front contact 209 of relay 3R, wire 194, front contact 195 of relay 2AY, upper winding of relay 2AN, and back contact 160 of relay 2R, to (-).

It will be noted that the picking up of relay 4BY, responsive to the designation of the entrance point for the route being set up, opens the 75

reverse branch of the initiating network for the route from signal 10 to signal 17 via crossover 4ts at back contact 43.

The track switches are positioned and the signals are cleared for the route just described in a manner which has heretofore been considered with reference to the description of certain typical circuits.

The picking up of relays 3R and 13XR in setting up that route, opens the circuit for relay 3YY at back contacts 23 and 22 respectively to cause relay 3YY to remain dropped away until the portion of the route with which it is associated is released.

15 In setting up a route from signal 10 to signal 13 at a time when the normal conditions of the system exist, the actuation of exit button 13XB, in setting up that route, causes the dropping away of relay 3YY by opening the circuit for that relay at contact 21 of button 13XB (see Fig. 1B), and the dropping away of relay 3YY closes the reverse branch of the initiating network at back contact 197 to allow a circuit to be completed for relay 13XR.

25 *Limitations of through route control.*—In connection with the entrance-exit control of switches and signals of a track layout, one or more stretches of the main track connecting with the track layout may be provided with block signals 30 or otherwise arranged for train movement for one normal direction of traffic only; and while trains may be moved into this stretch of track in a direction opposite to the normal direction of traffic for a limited distance for switching or shunting movements, such train may not continue on its way. It is contemplated that the through route control characteristic of this invention will be used by the operator primarily for through train movements, as distinctive from shunting 35 40 train movements; and it is considered desirable to limit the through route control to a situation where a through and continued train movement is possible, thereby avoiding the contingency that the operator may inadvertently actuate the wrong exit button in connection with a through route operation and direct a train into a stretch of track against the normal direction of traffic where the train may not continue on its way as the operator may have expected. Accordingly, means is provided whereby the through route control is not effective to set up a through route into a stretch of track against the normal direction of traffic.

To illustrate this mode of operation, it is assumed that the upper track shown in Figs. 3B and 1C connects with a stretch of main track to the right of signal 16 which is equipped with block signals for one direction of train movement, or is otherwise limited for west-bound traffic only, while the stretch of track beyond signal 17 for the lower track is equipped for east-bound traffic. In accordance with this invention, provision is made so that a route for an east-bound train can be set up between signal 14 and signal 16 by actuation of the entrance button 14NB and the exit button 16NB, when desired for shunting or switching movements; but that no through route for eastbound traffic can be set up to signal 16, although a through route can be set up from signal 10 past the intermediate signal 14 to the signal 17 over the crossover 4 in the reverse position in the manner already explained.

As a means for providing such limitation of 75 the end-to-end control a special route selector

relay 4YY (see Fig. 1C) is provided to open the branch of the initiating network extending toward exit relay 16XR when setting up a route by end-to-end control for east-bound traffic having a possible exit point at signal 16. Thus, 5 when an operator actuates button 10NB for the designation of an entrance point in setting up a route, under normal conditions, relay 4YY is picked up, after relays 10NR and 2AY have been picked up, by the energization of a circuit 10 closed from (+), through a circuit including front contact 181 of relay 10NR (see Fig. 1A), back contact 182 of relay 10XR, back contact 183 of relay 2R, front contact 184 of relay 2AY, wire 196, back contact 185 of relay 3R, back 15 contact 186 of relay 12XR, front contact 188 of relay 2NCR and front contact 187 of relay 1T connected in multiple, front contact 189 of relay 1T, wire 190, back contact 191 of relay 14M, back contact 210 of relay 14XP, back contact 20 211 of relay 14NR, and winding of relay 4YY, to (—). The picking up of relay 4YY opens the branch of the initiating network extending toward the relay 16XR at back contact 212 to prevent the energization of relay 16XR in case 25 the exit button 16XB is depressed when such an entrance point has been designated.

It is provided, however, that relay 14NR can be picked up when button 14NB is depressed in a manner similar to that described in detail for 30 the picking up of relay 16NR, at a time when the normal conditions of the system exist; and the picking up of that relay feeds energy through the initiating network to relay 16XR because the circuit for relay 4YY is opened by the picking up of relay 14NR at back contact 211 to provide that relay 4YY remains dropped away as long as a route is set up from signal 14 to signal 16.

Upon actuation of exit button 16XB, after an 40 entrance point for a route has been designated by the actuation of button 14NB, relay 16XR is picked up by the energization of a circuit closed from (+), through a circuit including front contact 39 of relay 14NR, back contact 40 of relay 45 14XR, back contact 212 of relay 4YY, back contact 213 of relay 4R, winding of relay 16XR, back contact 214 of relay 16NR, and contact 215 of button 16XB closed in a depressed position, to (—). Upon the picking up of relay 16XR a 50 stick circuit is closed at front contact 216 of relay 16XR to shunt contacts 214 and 215 out of the circuit just described.

The picking up of relay 16XR causes the picking up of relay 4AN, and the eventual positioning of the track switches associated with crossover 4ts and the clearing of signal 14 in a manner characteristic of the system as heretofore described.

Interlock between entrance and exit relays of adjoining interlocked groups.—Suitable electric interlocking circuits for the exit relays for the same signal location of adjoining interlocked groups are provided so that the operator may not unintentionally manipulate the buttons to 60 clear opposing signals of the adjoining interlocked group simultaneously for train movement in opposite directions toward the same signal locations, such a situation being inconsistent with the continued movement of both trains. A route can 65 not be set up, for example, from the signal 10 to signal 12 at the same time that a signal is set up from signal 16 to signal 14. In this connection, a train may be moved into the route from signal 10 to signal 12 at one time, and 70 75

another train may be subsequently moved into the other route from signal 16 to signal 14, if occasion should require, but the exit relays of these adjoining interlocked groups are interlocked so that such routes for opposing train movements cannot be established at the same time.

Similarly, provision is made so that the entrance relays for routes in opposite directions originating at the same signal location cannot be energized at the same time, since these routes cannot be used, and one of these entrance relays energized by mistake would have to be manually restored. This constitutes an additional check upon the operator's manipulation.

This feature is provided by a direct interlock in the circuits for the entrance and exit relays for the adjacent entrance and exit points respectively. That is, entrance relay 14NR for example, cannot be picked up when entrance relay 12NR is picked up, because the circuit for relay 12NR includes back contact 36 of relay 12NR (see Fig. 1B), and entrance relay 12NR cannot be picked up when entrance relay 14NR is picked up, because the circuit for relay 12NR includes back contact 132 of relay 14NR (see Fig. 1F).

A similar condition exists in regard to the exit relays, that is, relay 14XR for example, cannot be picked up when relay 12XR is picked up because the pick-up circuit for relay 14XR includes back contact 138 of relay 12XR (see Fig. 1E); and exit relay 12XR cannot be picked up when exit relay 14XR is picked up because the pick-up circuit for relay 12XR includes back contact 220 of relay 14XR (see Fig. 1C).

Thus, in a similar manner, an interlock is provided between each of the interlock groups included in the track layout for which the system is provided.

Having described the present invention as applied to a particular problem encountered in practice, it is desired to be understood that the invention is not limited to the specific form shown, and that additions, modifications, and changes can be made to adapt the system provided by the present invention to various requirements of practice, without in any manner departing from the spirit or scope of the present invention, except as limited by the scope of the following claims.

What we claim is:

1. In an interlocking system of the character described in which a track layout provides a plurality of routes extending between entrance and exit points, the routes being connected end-to-end to form a composite route; manually operable contact means for each of the entrance and exit points, an entrance relay for each entrance point, an exit relay for each exit point, means for energizing each entrance relay when the contact means for that entrance point is actuated, only if the entrance relay for the opposite direction of traffic for the route adjacent to that entrance point is dropped away, means for energizing each exit relay when the contact means for that exit point is actuated, if there is an entrance relay picked up for an entrance point designated in an available route associated with that exit point, only if the exit relay for the opposite direction of traffic for the route adjacent to that exit point is dropped away, and route establishing means dependent upon the picking up of an entrance and an exit relay for each route for setting up a route between the entrance and exit points thus designated, whereby it is impossible to set up contemporaneously two adjacent routes for conflicting directions of traffic.

2. In a switch and signal control system, a plurality of interlocked groups located end to end and each comprising a plurality of track switches for setting up different routes and signals for governing traffic in opposite directions over such routes so as to have a signal at the entrance to each of the adjacent routes which must be cleared in order to allow the passage of a train through such adjacent routes, manually operable contact means for each of said signal locations, route establishing means for each interlocked group responsive to the joint actuation of a manually operable contact means for an entrance point and a manually operable contact means for an exit point for operating the track switches in its interlocked group to set up a route between such points and clear the signal at the entrance end, and means controlled by each route establishing means, when a route is established in any particular direction in its interlocked group, for preventing the response of the route establishing means for an adjacent interlocked group to its manually operable contact means for setting up an adjacent route for the opposite direction of traffic.

3. In a switch and signal control system of the entrance-exit type described for governing traffic through a track layout having a plurality of track portions adjoining end-to-end to form through routes, each portion having signals at its ends, certain ones of which may become intermediate signals in some through route, and each portion providing a route between entrance and exit points defined by the location of the signals; manually operable contact means for each of the entrance and exit points; route establishing means responsive to the joint actuation of the contact means for the entrance and exit points of the route extending through each of the portions for setting up a route within that portion; route establishing means responsive to the combined actuation of the contact means for the entrance to one track portion and the exit for a subsequent track portion, for traffic in the same direction, for setting up a through route extending between those designated entrance and exit points, said route establishing means including through route circuit connections associated with each intermediate signal and having contacts of track relays included in said circuit connections; whereby, in setting up a route for an approaching train by through route control, it is impossible to clear a signal for a preceding train occupying a portion of that proposed route; and circuit means for automatically restoring to normal said route establishing means for each of the successive track portions in turn for a through route upon the passage of a train through those respective portions.

4. In a switch and signal control system of the entrance-exit type for governing the power operation of track switches and the clearing of signals for setting up routes between entrance and exit points, a track layout providing a plurality of routes some of which routes are adjoining end-to-end to form through routes past one or more intermediate signals, manually operable contact means for each entrance and exit point, an exit relay for each exit point, an initiating circuit network effective upon the actuation of said contact means for an entrance point to condition each of said exit relays included in an available route or through route emanating from a designated entrance point so that such exit relay can be picked up upon actuation of said contact means asso-

- ciated therewith for designation of an exit point for such route, said initiating circuits including through route connections associated with each intermediate signal and having contacts of track 5 relays and contacts operated in accordance with the position of the track switches included in said circuit connections to prevent energization of exit relays for any through route over a track section occupied by a train, route establishing means responsive to the picking up of the exit relay for the exit end of a through route for setting up a route within each interlocked group corresponding with that portion of the through route included between the entrance and exit ends designated, and circuit means for automatically restoring said route establishing means to normal upon passage of a train past those portions of the through route with which such route establishing means is associated.
- 20 5. In a switch and signal control system of the character described for a track layout having a plurality of conflicting routes extending between signal locations constituting entrance and exit points and having a plurality of interlocked groups adjoining end-to-end with signals at such adjoining ends constituting intermediate signals, manually operable contact means for each entrance and exit point, an exit relay for each exit point, an initiating circuit network effective upon designation of an entrance point by the actuation of said contact means for that entrance point to condition each of said exit relays included in a possible route available emanating from that entrance point so that such exit relay can be picked up upon actuation of said contact means associated therewith, or upon the completion of a route up to that point from the exit point designated in setting up a through route, only provided each intermediate signal between such designated entrance and exit points for a through route is at stop and also only provided said manually operable contact means for such intermediate signal has not been actuated, and route establishing means responsive to the picking up of each 45 exit relay for setting up a route within that interlocked group which is a portion of a route designated by the actuation of said contact means for the entrance and exit points.
6. In a switch and signal control system of the 50 entrance-exit type described for governing traffic in a given direction from an entrance point to an exit point through a first interlocked group, and from an entrance point to either of two exit points through a second interlocked group, the first and second interlocked groups being respectively adjoining end-to-end; manually operable contact means for each entrance and exit point; route establishing means responsive to the combined actuation of said contact means for an entrance and an exit point for each of the interlocked groups for setting up a route between those points within that group; through-route establishing means responsive to the combined actuation of said contact means for the entrance 65 point to the first interlocked group and a particular one of the exit points for the second interlocked group for setting up a route between those points including the entrance point of the second interlocked group; a selector relay which, when energized, prevents the setting up of a through route including the entrance point of the second interlocked group due to the combined actuation of the contact means for the entrance point to the first interlocked group and the contact means for the other exit point of the second interlocked
- group, and which, when deenergized, allows the setting up of a route from the entrance point in the second interlocked group to said other exit point; and circuit means for energizing said selector relay when said contact means is actuated for the entrance point to the first interlocked group, such circuit means being rendered ineffective for the energization of that relay if the contact means for said entrance point to the second interlocked group is actuated.
7. In a switch and signal control system of the entrance-exit type for a track layout including a plurality of interlocked groups located end to end and thereby affording different routes in each group between signal locations governing traffic in that group as well as affording various through routes past one or more intermediate signal locations, manual control devices for said signal locations operable to designate such locations as an entrance and/or exit point, route establishing means associated with each interlocked group acting in response to the operation of a manual control device to designate any given signal location as an entrance point followed by the actuation of a manual control device to designate any other signal location of that interlocked group as an exit point of any establishable route originating at said entrance signal location to control the power operation of the track switches as required to set up a route connecting such signal locations, means acting in response to the actuation of a manual control device to designate a given signal location as an entrance point to render effective for operation the manual control device at the exit ends of the various available routes and through routes originating at said signal location and also acting to condition for operation said route establishing means for the associated interlocked group and each succeeding interlocked group including a route or routes forming a part of some through route originating at said given entrance signal location, such conditioning operation of the succeeding interlocked group being effective with respect to each intermediate signal location included in the various through routes originating at said given entrance signal only if a circuit path corresponding with said intermediate signal is closed, means including contacts of track relays and contacts operated in accordance with switch positions for opening said circuit path for an intermediate signal when a route terminating at that signal is occupied by a train irrespective of its direction of movement, whereby the operation of a manual control device to designate the exit signal location of some through route causes the associated route establishing means to set up a route in accordance with said conditioning, and electro-responsive means for each signal which may become an intermediate signal location in some through route acting in response to the setting up of a route in its interlocked group in advance of such signal by its associated route establishing means to cause the clearing of its associated signal and perform an exit operation for the route establishing means of the next preceding interlocked group included in that through route.
8. In a switch and signal control system of the entrance-exit type for a track layout including power-operated switches and signals forming a plurality of interlocked groups located end-to-end and thereby affording different routes in each group between signal locations governing traffic in that interlocked group as well as affording various through routes past one or more inter-

- mediate signal locations, track circuits associated with the switches and signals of each interlocked group, each track circuit being provided with a track relay, manual control devices for said signal locations operable to designate such locations as an entrance or exit point, route establishing means associated with each interlocked group acting in response to the operation of a manual control device to designate any given signal location as an entrance point followed by the actuation of a manual control device to designate any other signal location of that interlocked group as an exit point of any establishable route originating at said entrance signal location to control the power operation of the track switches as required to set up a route connecting such signal locations, through route circuit means interconnecting the route establishing means of adjoining interlocked groups at points corresponding to those signal locations which may become intermediate signal locations in some through route, whereby the operation of a control device to designate any given entrance signal location acts on the route establishing means for each group in any through route originating at that entrance point so that the actuation of a control device to designate the exit point of a through route causes the operation of the route establishing means for each interlocked group forming part of such through route, and track relay contacts included in said through route connections effective to open any given through route connection associated with an intermediate signal whenever a route over a stretch of track in the rear of such signal is occupied by a train irrespective of its direction of movement.
9. In a switch and signal control system of the entrance-exit type having a track layout with a plurality of routes extending between entrance and exit signal locations, said track layout affording at least two alternative routes between a common entrance and exit signal locations, control buttons for said entrance and exit signal locations manually operable to designate any signal location as an entrance point or an exit point, initiation circuits energized in response to the actuation of a control button to designate an entrance point for preselecting the position of the trailed switches in all available routes originating at that entrance point, said initiation circuits normally acting in the case of said alternative routes to preselect the position of the switches for a first one of said alternative routes in preference to a second alternative route, completion circuit means energized in response to the actuation of a control button to designate the exit point of a particular one of such available routes originating at a designated entrance point for acting in accordance with the preselection operation of said initiation circuit with respect to that particular route to cause the power operation of the track switches to establish such route, a relay having contacts for opening the initiation circuit for said first alternative route but leaving intact the initiation circuit for said second alternative route, to thereby cause said initiation circuits to preselect the position of the switches as required for said second alternative route in preference to the first alternative route contrary to the normal preference of preselection in the initiation circuits, a normally closed energizing circuit for said relay for causing said relay to open its contacts, and contacts included in said energizing circuit for deenergizing said relay whenever said second alternative route is not available for use.
10. In a switch and signal control system of the entrance-exit type having a track layout with a plurality of routes extending between entrance and exit points, said track layout affording at least two alternative routes between a common entrance and a common exit point, control buttons for said entrance and exit points manually operable to designate an entrance point or an exit point, initiation circuits energized in response to the actuation of a control button to designate an entrance point for preselecting the position of the trailed switches in all available routes originating at that entrance point, said initiation circuits inherently acting in the case of said alternative routes to preselect the position of the switches for a first one of said alternative routes in preference to a second alternative route, completion circuit means energized in response to the actuation of a control button to designate the exit point of a particular one of such available routes and acting in accordance with the preselection operation of said initiation circuit with respect to that particular route to cause the power operation of the track switches to establish such route, a relay having contacts for opening the initiation circuit for said first alternative route to thereby render the second alternative route the preferred route normally to be established upon the designation of its entrance and exit ends, and circuits for controlling said relay to normally open its contacts but to close its contacts whenever said second alternative route is not available for use and said first alternative route can still be used.
11. In a switch and signal control system of the entrance-exit type for a track layout including power operated track switches and signals forming a plurality of interlocked groups located end-to-end and thereby affording different routes in each group between the signal locations governing traffic in that group as well as affording various through routes past one or more intermediate signal locations, manual control devices for said signal locations operable to designate such locations as an entrance or exit point, route establishing means associated with said interlocked groups comprising initiating circuits energized in response to the operation of a manual control device to designate any given signal location as an entrance point for preselecting the positions of certain switches in the various routes and through routes originating at said designated entrance point, and comprising completion circuit means responsive to the operation of a manual control device to designate any given signal location as the exit point of a route or through route originating at a designated entrance point to cause the operation of the switches in that route in accordance with said preselection operation for establishing such route or through route, and circuit means responsive to the operation of a manual control device to designate an entrance signal location at the entrance to a plurality of available diverging through routes originating at that entrance point for opening the initiating circuits for a particular one of such through routes, said means permitting the use of such initiation circuits for the establishment of routes within any single interlocked group forming a part of that particular through route.
12. In a switch and signal control system of the entrance-exit type for a track layout including power operated switches and signals forming a plurality of interlocked groups located end-to-end and affording different routes in each group between the signal locations governing traffic in

that interlocked group and also affording at least two diverging through routes originating at a given signal location, manual control devices for said signal locations operable to designate such 5 locations as entrance and exit signal locations, route establishing means associated with said interlocked groups for governing the power operation of switches and the clearing of signals including initiation and completion circuit means, 10 said initiation circuit means being responsive to the actuation of a manual control device to designate any given entrance signal location to pre-select the position of trailed switches in all available routes originating at that entrance signal 15 location and render effective for actuation the manual control devices for the exit ends of such routes or through routes, and said completion circuit means being responsive to the actuation of a manual control device that has been rendered 20 effective for the exit end of a route or through route originating at a designated entrance signal location to initiate operation of the switches in succession in accordance with the energized condition of said initiation circuits and preselected 25 position of the trailed switches to thereby establish said route or through route and clear the signals governing traffic thereover, relay means associated with a particular one of the diverging through routes originating at said particular signal 30 location for opening the associated initiation circuit for that through route, and energizing circuit means responsive to the actuation of the manual control device for said particular signal location to designate it as an entrance signal 35 location for energizing said relay means to thereby prevent the actuation of a manual control device to designate the exit end of that particular through route from being effective to establish such through route, and contacts associated with 40 the intermediate signal location governing traffic over that interlocked group where said through routes diverge for opening said energizing circuit means of said relay means to allow said initiation circuits to be employed for the establishment of 45 routes in the associated interlocked group.

13. In a switch and signal control system of the character described for a track layout having a plurality of interlocked groups, each comprising conflicting routes extending between signal locations constituting entrance and exit points, such 50 interlocked groups adjoining end-to-end with the signals at the adjoining ends constituting intermediate signal locations, manually operable contact means for each signal location operable to 55 designate the corresponding location as an entrance or exit point, an exit relay for each exit point, route establishing means for each interlocked group comprising initiation circuit means and completion circuit means, said initiation 60 circuit means acting in response to the actuation of a manual control device to designate an entrance signal location to condition for energization the exit relays at the ends of all available routes originating at the designated entrance point, said 65 completion circuit means acting in response to the energization of an exit relay energized upon the designation of the exit point of a given one of such available routes to cause the establishment of that particular route and the clearing of the 70 signal at the entrance thereto, through route circuit means for interconnecting the initiation and completion circuits for adjoining interlocked groups at the various intermediate signal locations, whereby the designation of the entrance 75 and exit ends of any given through route causes

the establishment of the routes of the various interlocked groups forming parts of such through route, and means associated with each intermediate signal location for opening the through route connection for any given intermediate signal 5 location having its signal cleared, said means maintaining such through route connection opened until after the initiation and completion circuits for the associated interlocked group governed by that signal have been effectively de- 10 energized following the manual or automatic cancellation of that route.

14. In a switch and signal control system of the entrance-exit type for a track layout including power operated track switches and signals forming a plurality of interlocked groups located end-to-end and affording different routes in each interlocked group between the signal locations governing traffic in that group as well as affording various through routes past one or more intermediate signal locations, self-restoring manually operable control buttons associated with said signal locations for designating such locations as entrance or exit points, an entrance stick relay associated with each signal location which may 20 become an entrance point, an exit stick relay associated with each signal location which may become an exit point, pick-up circuits for each of said entrance stick relays closed upon the actuation of its associated control button to designate 25 an entrance point, stick circuits for each of said entrance relays controlled by a track circuit in advance of its associated signal so as to be automatically opened upon the passage of a train past 30 that signal, route establishing means associated 35 with each of said interlocked groups comprising initiation and completion circuit means, said initiation circuits being energized in response to the picking up of an entrance stick relay for any given entrance signal location for preselecting the 40 position of certain switches in the various routes originating at said entrance point and conditioning for energization the exit relays for the ends of such routes, pick-up circuits for each exit relay 45 closed upon the actuation of its associated control button to designate an exit point only if such exit relay has been conditioned for energization by such initiation circuits, the picking up of said exit relay closing its stick circuit, said completion circuit means acting in response to the energization 50 of an exit relay for the end of a particular route to cause the establishment of that particular route in accordance with said preselection effected by the energization of the associated initiation circuit, through route circuit means associated with 55 each intermediate signal location for interconnecting the route establishing means of the adjoining interlocked groups, to thereby provide the establishment of a through route in response to 60 the actuation of the control buttons to designate the entrance and exit ends of such through route, electro-responsive means associated with each intermediate signal location acting to temporarily open the through route connection for 65 that intermediate signal location when a train passes such signal location deenergizing the corresponding entrance stick relay and restoring that signal to stop, to thereby insure the deenergization 70 of the exit relay for the exit signal in spite of the energization of the initiation circuits for any route connecting with that intermediate signal location.
